UNITED STATES PATENT OFFICE.

TALBOT G. MARTIN, OF CHICAGO, ILLINOIS, ASSIGNEE, BY MESNE ASSIGNMENTS, TO FIRST TRUST AND SAVINGS BANK, TRUSTEE, OF CHICAGO, ILLINOIS.

COMMON BATTERY TELEPHONE-EXCHANGE SYSTEM.

1,188,804.

Specification of Letters Patent. Patented June 27, 1916.

Application filed December 16, 1913. Serial No. 278,816.

To all whom it may concern:

Be it known that L. Talbot G. Martin, a citizen of the United States of America, and resident of Chicago, Cook county, Illinois, have invented a certain new and useful Improvement in Common-Battery Telephone-Exchange Systems, of which the following is a specification.

My invention relates to automatic or semi-automatic telephone systems in general, but more particularly to automatic telephone systems in which each subscriber is provided with means for controlling or operating the exchange apparatus in such manner that a connection with the desired subscriber's line may be obtained without the assistance of an operator, and especially to automatic telephone systems of that particular character in which the expedient by which the subscribers automatically operate the exchange apparatus consists in the transmission from any calling subscriber's station of a suitable number of electrical impulses, each subscriber being provided with means for producing during an intermittent make and break action in grounded line-circuits including either one or both sides of his line.

Generally stated, the object of my invention is the provision of an improved and highly efficient automatic telephone system of the foregoing general character in which all electric currents, both for switching and signalling purposes, as well as for talking purposes, are supplied from suitable sources located at the exchange or central station.

Special objects of my invention are the provision of an improved common battery connector for automatic telephone exchange systems; the provision of improved circuits in a common battery connector for automatic telephone exchange systems; and the provision of certain details and features of improvement tending to increase the general efficiency and serviceability of automatic telephone exchange apparatus of this particular character.

In many ways my present invention contemplates certain improvements on the automatic telephone exchange apparatus described and claimed in my prior application, Serial No. 278,816, filed September 16, 1905. In said prior application I have shown and described a new common battery automatic telephone exchange connector, together with various novel relay and circuit arrange-

ments, as well as an arrangement whereby telephone service may be had between the subscribers of two separate and distinct and different kinds of exchanges, namely an automatic telephone exchange and a manual bell-board exchange. In the present application I have, however, invented and claimed certain improvements which are necessary in order to afford a common battery automatic telephone exchange connector, and the improved relay and circuit arrangements, to the calling of service between subscribers of the same automatic telephone exchange, or between any automatic telephone exchange subscribers having switching devices for transmitting both switching and signalling electrical impulses.

To the foregoing and other useful ends, my invention consists in matters hereinafter set forth and claimed.

Figure 1 illustrates diagrammatically the circuits and devices involved when one of the lines of an exchange involving my improved common battery apparatus has called a second line of the same exchange; and this figure shows a calling sub-station #400, and a called sub-station #220, a first-selector A at the left of the line X--X, a connector C to the right of said line, and a first-selector D to the right of the line Y--Y, permanently identified with the called line. Fig. 2 shows the first-selector mechanism in perspective, together with the circuit connections, in a way to give a clear idea of the relative positions of the operative parts as they are assembled in practice about a non-magnetic switch form of suitable character; and the banks of trunk-line terminals are also shown in position immediately below the switch. Fig. 3 illustrates the connector in a similar manner.

The sub-station equipments employed in connection with common battery systems of the nature in question are all of a well-known and suitable type. Sub-station #400, for example, is at once recognized by the peculiar switch hook 2 which is made with a number of cam-like arms 3, 4, 5 and 6. The primary circuit at said station comprises the main line-conductors in series, and contains the primary winding 7 of the induction-coil 8, a transmitter 9, a couple of springs 10 and 11 identified with the signalling button 12, and two springs 13 and 14 through the function of which the said cir- 110

cuit is maintained closed or opened, depending upon whether the hook is up or down. Said hook is suitably pivoted at its inner end 15, and is forced to rise whenever the weight 5 of the receiver 16 is removed from it, by a suitable switch-hook spring not shown. The secondary circuit comprises the said receiver 16 in series with the secondary winding 17 of the induction-coil 8 in a permanently 10 closed local circuit. The ringer circuit at said sub-station includes the ringer 18, the ringer circuit springs 19 and 20, and the condenser 21. This circuit, while the switch-hook is down, is closed by the cam-arm 4 that presses the ringer circuit springs 19 and 20 into contact, and is normally bridged across the main line. While the hook is up, however, the said bridge is open, because the said springs 19 and 20 spring 15 apart after the cam-arm 4 is removed from the spring 19. The cam-arm 5 controls the continuity of a ground circuit between the so-called ground-post 22 and the ground terminal G, through the medium of two 20 springs 23 and 24 that are included in said circuit. The sub-station has three other springs 25, 26 and 27 which are known as the release-springs and by means of which the main line-conductors may be grounded simultaneously 25 for the purpose of restoring the exchange apparatus. When the hook is depressed, as it descends, the said release-springs are forced together by the cam-arm 3 which latter then engages the laterally-projecting extremity 28 upon the spring 25. The engaging portions of the cam 3 and spring 25 are constructed with their surfaces at an angle with each other, so that when the hook goes down one surface of the 30 projection 28 is engaged and when it rises the opposite surface comes into use. In this way, when the hook goes down, the spring 25 is forced onto the springs 26 and 27, and when the hook rises it is shoved in the opposite direction. Therefore, at the limit of 35 each stroke of the hook, the cam-arm 3 clears the spring 25. The calling device employed by the subscriber comprises two push-buttons 29 and 30, two contact-points 31 and 32, 40 two springs 33 and 34 and the so-called ground-post 22. The spring 33 and contact 31 are normally in contact, as well as the spring 34 and contact 32. But when the button 29 is pressed the spring 33 is separated from the contact-point 31 and connected with the ground-post 22, and when the button 30 is pressed the second spring 34 is pressed onto the same ground-post, after 45 said spring leaves the contact-point 32. It will be understood, of course, that any suitable means can be employed for regulating the transmission of impulses over the line circuits, so as to obtain the desired results and the described mode of operation. 50 For example, suitable and well-known means

can be provided for insuring a proper transmission of current when the receiver 16 is placed on its switch-hook.

In Fig. 2 the first-selector A is shown with the bank 50 of trunk-line terminals 51 beneath it, while the private-bank 52 of private-bank line-terminals 53 is located just above said bank 50. The vertical switch-shaft 54 is disposed on the front of the switch-frame and retained connected therewith by bearings which are not shown. The shaft may be moved longitudinally in said bearings, and then rotatively, by ratchet and pawl mechanism. The longitudinal movements, when the switch first comes into use, 70 are always produced before the rotary motion. Among the functions of the shaft that of a holder for the line-wipers 55 and 56, and for the private-wiper 57, is an important one. The former two comprise a 75 set distinct from the latter, but both sets are within range of the contacts of their respective banks 50 and 52. Said wipers are not only insulated from the shaft, but from each other as well. Among the details that 80 are associated with the shaft is a cam piece 58 which is of a split sleeve design and secured to the shaft by a screw 59. The general shape of said cam, in section at right angles to the shaft, is that of an elongated 85 oval with the sharper apex at the side farthest away from the screw 59. Said cam abuts on a hub 60 that is shrunk to the shaft near the middle of the latter. This hub 90 carries a set of longitudinal teeth 61 that 95 serve, as will be disclosed, to enable the forward rotation of the shaft, and as a locking means against backward rotation of same. On the neck portion of said hub there are formed a set of circular teeth 62 that 100 serve as a means through which the raising of the shaft is accomplished, and for locking it when raised. These circular teeth are traversed by a groove 63 into which the 105 end of a so-called shaft-rest 64 normally 110 projects; but when the shaft is rotated any one of the circular teeth 62 which may be at the proper height slides onto the end of said rest. The end of said rest, of course, is adapted to fit the grooves between said circular teeth. Its upper surface lies in a horizontal plane, but the under side of the end is chamfered to form a wedge that corresponds to the upper slope of the circular teeth. Above the hub 60 the shaft 54 carries an arm 65, known as the normal-post-arm, and which, while the switch-shaft is at 115 rest, and while the shaft-rest occupies the slot 63, is retained against the normal-post 66 by the coiled spring 67. The said normal-post-arm normally retains an off-normal spring 68 in contact with a contact-point 69, located beneath it; but when the shaft is raised said spring flexes into contact with a 120 grounded contact-point 70 instead. 130

Among the magnets allotted to the first-selector some are used as relays and others as operative-magnets. The magnets 71 and 72 are of the former kind and are known as the vertical and rotary line-relays. By means of their respective armatures 73 and 74, the former controls the spring 75, and the latter the spring 76, with respect to the ground spring 77. Said springs are comprised in energizing circuits of magnets by means of which the operative parts that raise and rotate the shaft are controlled. The magnet 78, armature 79, and springs 80, 81 and 82 constitute the bridge-opening relay, or bridge-cut-off-relay as it is called, and the magnet 83 with its armature 84 and springs 85 and 86 is the back-release-relay which is used for restoring the switch. Of the operative-magnets the magnet 87 is known as the vertical-magnet and has harnessed to it a so-called vertical-armature 88 supported by pivots 89 on the under side of said magnet. Whenever the coils 90 and 91 of said vertical-magnet become energized the armature 88 is attracted and when the magnetization ceases the retracting-spring 92 restores said armature to its normal position. The upward movement of the armature is limited by the pole pieces of the magnet-coils 90 and 91, and the lower limit is marked by a section of the switch-frame that passes under the arm 93. Said arm 93 is known as the vertical-arm and extends forwardly from the vertical-armature 88 of which it is a part. The vertical-arm carries on its end a so-called vertical-pawl 94 which, when the vertical-armature is attracted, engages one of the circular teeth 95 to raise the shaft. Normally, the under surface of the upper section of said pawl rests against a piece that is secured to the switch-frame and that retains the pawl away from the circular teeth. When the vertical-armature is attracted, as the pawl 94 rises a retracting-spring 95 thrusts the upward side of the pawl toward the circular teeth 95. As soon as said pawl clears its normal rest, and by the time that the vertical-armature strikes the pole-pieces, the vertical-pawl strikes with the rear surface of its upper section against a bumper piece—which latter constitutes a part of the switch frame—so that the shaft is prevented from being raised more than one notch at a time. Thus not only does the pawl 94 raise the shaft, but it also looks the same at the end of each stroke. The vertical-arm has also an L-shaped piece 96 on its under edge that engages a link 97 of flexible spring material. Said link has an aperture 98 in its front end and is secured to the armature 99 of one of the operative-magnets known as the relief-magnet. Said armature is suspended from the supports 101 and is normally retained by the spring 102 away from the pole piece of the release-magnet. A stop is suitably provided behind said armature to limit its movement when retracted. The first-selector-frame supports a peculiarly shaped mechanism 103 known as the double-dog. It is pivoted so that it may swivel about a vertical axis that passes through the pivots 104. On its front side said double-dog develops into two dogs 105 and 106, so situated and constructed that the former (105) may operate in conjunction with the circular teeth while the switch-shaft is raised and in its normal rotary position, and so that the latter (106) may coöperate with the longitudinal teeth 61 when the shaft is rotated. To the right of the pivots 104 the body of the double-dog extends rearwardly, and projecting down therefrom is an arm 108 that comes into play during the releasing of the switch. Near its extremity and on the upper side thereof a pin or lug 109 projects upwardly. Said lug is normally caught in the aperture 98 of the release-link 97, and because of the tension in the spring 102 the dogs 105 and 106 are retained away from the shaft. At the first stroke of the vertical-armature the link 97 is drawn away from the lug 109 by the piece 96, and then the double-dog is rotated by the retracting-spring 110, so that the arm 105 falls under the first circular tooth. Then when the vertical-armature returns to its normal position the said shaft is retained by said dog in its new position. The release-link 97, while the double-dog is free, rests with its end upon the lug 109, and out of locking engagement therewith. Then when the vertical-magnet is energized a second time the shaft is raised a second step. The dog 106, at the second stroke, then passes from under the first tooth to below the second tooth, holding the shaft in this position.

The release-magnet 111 is composed of two coils like the vertical-magnet 87, but for convenience of illustration only one coil is shown. If while the shaft is raised the said release-magnet should be energized, the release-armature 99, of course, is attracted and release-link 97 is thrust forward to catch the lug 109 in the aperture 98. Upon the deenergization of the release-magnet the retracting-spring 102 then withdraws the dogs 105 and 106 from the shaft, which latter being deprived of its only support then falls to normal position by its own weight. After the shaft is once raised it may be rotated by a second operative-magnet 112 known as the rotary-magnet. Said magnet has two coils 113 and 114, and unlike the vertical-magnet has its armature 115 pivoted in a vertical plane. Said armature 115 may be moved about a vertical axis that passes through the pivots 116. The limit of the movement of said armature toward the rotary-magnet is determined by the pole-

pieces of said magnet, which movement is produced by the rotary-magnet itself. The motion of the armature in the opposite direction is produced by the retracting-spring 117 and is limited by a switch-stop behind the so-called rotary-arm 118. This arm, like the vertical-arm, carries a so-called rotary-pawl 119. Similarly to the vertical-pawl, said rotary-pawl normally rests 10 against a stop that retains it away from the longitudinal teeth, and when the rotary-armature is attached said pawl is drawn into engagement with the longitudinal teeth by a spring 120 that is attached between the rotary-arm and the rear of said pawl. By the time that the rotary-armature strikes the pole-pieces of the rotary-magnet, the rotary-pawl also strikes a stop or bumping-post that locks the shaft against further advance 20 by the force of its own momentum. At the end of the first rotary step the dog 106 falls behind the first longitudinal tooth, so that when the rotary-pawl falls back the shaft is retained. It will be seen that as the shaft is rotated the vertical-dog 105 is withdrawn from the groove of the circular tooth which has been resting upon it, by the engagement of the rotary-dog 106 with the longitudinal tooth over which it has to slide; but at the 30 beginning of the rotation the tooth which has been caught by the vertical-dog slides onto the shaft-rest 64, and in this way the shaft is still held raised after the rotation begins. The rotary-armature is provided 35 with a so-called interrupter-finger 121 that separates the interrupter-springs 122 and 123 whenever the rotary-armature is attracted, and also with a rotary-armature-finger 124 that exercises certain controlling influences over the armature 125 of the last one of the operative-magnets, namely, the private-magnet 126. The said private-armature 125 works in a vibratory manner about a horizontal axis that passes through 40 the supporting point 127. It is formed with a forwardly-projecting arm 128, the latter having two flat surfaces in an approximately horizontal plane. Furthermore, the end of the said arm is bent at a right angle downwardly and carries certain mechanical details, namely, a lateral arm 129 which is designed to control circuits comprising the private-springs 130, 131 and 132, and a tooth-escapement which includes 50 two flexible springs 133 and 134 each of which is riveted by one end to the arm 128, one on the upper side and the other on the lower. The upper spring is straight and has formed on its end two tooth projections 135 and 136 which extend downwardly, while the lower one is bent down and at a right angle again to the front. This double angle on the lower spring is provided in order that the latter may clear the bent portion 60 of the private-arm against which por- tion said spring rests with a degree of tension, and also in order that there may be space in front of said bent portion to receive two other tooth-shaped upwardly-projecting pieces 137 and 138 that are formed 70 on the forward end of the escapement-spring 134, and which are sustained in juxtaposition to the upper teeth, but slightly to the rear thereof. A retracting-spring 139, suitably located, holds said armature normally away from the private-magnet pole-piece. A well-known auxiliary switching mechanism common to such switches is the so-called side-switch. It is shown in connection with the first-selector A and comprises an arm 140 which is secured to the switch-frame in such a manner that it may be made to swing about the pivots 141. The right extremity of said arm is drawn out into a finger 142 that works in conjunction with the escapement-teeth previously described. Said teeth, in a manner to be described, reduce the outward movement of the side-switch, by means of said finger, to a step-by-step motion, which movement is 80 produced by a retracting-spring 143. 85

At the base of the finger 142 a lug 144 that is bent to the front is adapted to strike the cam 58 at a suitable time. Whenever the shaft is rotated, however, said cam is carried 95 beyond the reach of said lug. Near its left extremity the arm 140 carries a number of wipers 145, 146, 147 and 148 suitably mounted upon a pin 149 and insulated therefrom and from each other. Said wipers are 100 known as the side-switch-wipers and are adapted to be operated by the private-magnet and escapement device previously explained. If the private-magnet is energized once the private-armature is drawn down 105 once and restored to its normal position. The escapement-finger 142 then passes from behind the tooth 137 onto the rear of the tooth 135 at the downward stroke of the private-armature 125 and from behind the 110 latter tooth at the return stroke. As soon as the escapement-finger clears the latter tooth the retracting-spring 143 draws the side-switch to the second position where it is stopped when the lug 144 strikes the cam 58. 115 Immediately then, when the rotary-magnet energizes, the shaft is rotated, and the cam 58 passes away from the lug 144. Then the finger 142 of necessity falls against the tooth 138, because of the tension in the spring 143. The rotation of the shaft results when the rotary-armature 115 is attracted by the rotary-magnet. At the same time the rotary-armature-finger 124 depresses the private-armature 125 and causes the finger 125 120 142 to disengage from the tooth 138 and to advance against the tooth 136. Then as the rotary-armature returns to normal, when the rotary-magnet deenergizes for reasons to be disclosed, the private-armature, upon fol- 130

lowing the finger 124, permits the escapement-finger 142 to escape from the last tooth 136, thus permitting the side-switch to pass to third position with the said finger 142 resting against the side-switch-stop 150. In their normal positions the side-switch wipers 145, 146, 147 and 148 engage, respectively, with the contact-points 151, 152, 153 and 154, in the order named. This position is known 5 as the first position of the side-switch, at which time it will be clear the finger 142 is held behind the escapement-tooth 137. In the second position, while the said finger is between the teeth 137 and 138, the said side-switch-wipers engage instead with the contact-points 155, 156, 157 and 158, respectively. And when the said finger 142 falls against the stop 150 the wipers change their positions into contact with contact-points 10 159, 160, 161 and 162, respectively. Between the pivots 141 and the wiper supporting pin 149 a rearwardly-extending arm 163 on the side-switch-arm 140 pivotally supports at its end a link 164 the other end of which, being 15 bifurcated, engages with the lower end of the double-dog arm 108. The end of the double-dog-arm 108 is constructed somewhat in the shape of an inverted T. Should the release-magnet be energized while the side- 20 switch is in third position and, of course, while the shaft is rotated, the release-link 97, being attached to the release-armature 99, is thrust forward when the release-armature is attracted and catches the lug 106 in the aperture 98. Then when said release-armature is restored the spring 102, as before described, withdraws the dog 105 from the circular teeth 62. At the same time the arm 108 drives back the link 164 which 25 latter then rotates the side-switch-arm 140 about the pivots 141, against the tension of the side-switch-retracting-spring 133, and thus drives the finger 142 between the springs 133 and 134 and into a position behind the tooth 137, locking the side switch in the first or normal position. The switch shaft being unlocked by the removal of the dog support 106, and being thus left free, is 30 rotated by the coil-spring 67. At that instant the end of the shaft-rest enters the slot 63, at which time the shaft drops to its normal position. Therefore, after the switch has been operated the energization and de-energization of the release-magnet is sufficient to restore the switch completely to its 35 normal position. The line and private banks are each provided with ten rows of contact-terminals each row consisting of ten sets of contacts. Therefore, the shaft is so constructed that it may be raised to any one of ten levels and at each level it may be rotated ten successive steps in order that the wipers which it carries may be placed in connection with any one of the terminals of the ten sets 40 of contact-terminals in each level.

Fig. 3 shows the connector C which has many of its parts and circuits very similar to those of the first-selector. The line and private-banks 200 and 201 will be recognized. The switch-shaft 202 is identical with the 70 first-selector-shaft and is, therefore, provided with the line-wipers 203 and 204, the private-wiper 205, the cam 206, longitudinal and circular teeth 207 and 208, respectively, the normal-post-arm 209, and the coil-spring 75 210. The vertical movement of the shaft is, of course, produced by means of the vertical-magnet 211, vertical-arm 212, and vertical-pawl 213, the said vertical-arm 212 being supplied with the L-shaped piece 214, 80 as usual. The release-magnet 215, however, has its armature 216 on the right side instead of on the left side, which armature is constructed with an elongated portion 217 that reaches as far as the middle section of 85 the body of the double-dog 219. The release-link 220 is under the control of the L-shaped piece 214, but it is permanently secured to the switch-frame at the pin 221. The double-dog has the usual vertical and rotary locking-dogs 222 and 223, respectively, and the side switch-releasing-arm 224, while on the upper side of the body of the double-dog the lug 225 that is caught by the release-link 220 is in its usual position. When the 90 release-magnet of the connector is energized the release-link 220, instead of being thrust forward to catch the said lug 225, remains where it is and the double-dog 219 is struck by the armature 216 at the right of the 95 bearings 226, by the end 217 of the release-armature 216, so that the lug 225 is moved under the aperture 227 where it is then caught by the release-link 220. The double-dog 219 is thus prevented from returning to its operative position when the release-magnet becomes deenergized. The rotary-magnet 228 has a rotary-armature 229 that is quite simple, being provided with only a rotary-arm 230 upon the extremity of which 100 the rotary-pawl 231 is located. The rotation of the shaft is produced in the same mechanical manner described in connection with the first-selector, each time that the rotary-magnet is energized. The private-magnet 232, the private-armature 233, springs 234 and 235, escapement-teeth 236, 237, 238 and 239, and the arm 240 are identical with the similar parts of the first-selector. The said arm 240, however, controls 110 the private-springs 241, 242, 243 and 244, so that when the private-armature 233 is down the first two of said springs are separated and the last two brought into contact, and when the said armature is up the reverse takes 115 place—that is, the springs 241 and 242 close and the springs 243 and 244 separate. In the side-switch of the connector the side-switch-arm 245, escapement-finger 246, cam-lug 247, side-switch-stop 248, and retracting- 120

125

130

spring 249, at one side of the pivots 250, conform to like parts of the first-selector side-switch, while the member 251, link 252, side-switch-wipers 253, 254, 255, 256 and 257, together with their corresponding contact-points 258, 259, 260, 261 and 262, and 263, 264, 265, 266 and 267, and 268, 269, 270, 271 and 272, are on the other side of said pivots. It will be seen, therefore, that the connector side-switch-wipers are five in number, while those of the first-selector are only four in number. Among the relays of the connector the vertical-line-relay 273, through its armature 274, can flex the spring 275 against the ground-spring 276, and the spring 277 toward the spring 278, when said relay is magnetized. The rotary-line-relay 279, in the same manner, through its armature 280, when the former is magnetized, forces the spring 281 against the same ground spring 276 and permits the spring 278 in turn to bend toward the former spring 277. Said two springs 277 and 278 are so adjusted that they then come into contact when the two armatures 274 and 280 are attracted at the same time. The connector has a relay 282 and a retardation-coil 283 for purposes to be disclosed. The said relay 282 has an armature 284 by which the back-bridge-relay-springs 285 and 286 may be forced into contact. The ringer-relay 287 is a feature common to all connectors of the type under consideration and has the power when magnetized to disconnect the terminals of a called line from those of the calling line, and to place across the former the terminals of a ringer-generator E. This operation is accomplished by means of the armature 288 and the ringer-relay-springs 289, 290, 291, 292, 293, 294, 295, 296 and 297. A specially wound differential-relay 298, with two windings 299 and 300, is secured in the connector for the purpose of accomplishing certain desired functions, which functions will be disclosed later on. The armature 301 of said differential-relay 298 when attracted is designed to separate the differential-relay-spring 302 from its mate spring 303. At this juncture it will be remembered that the release of the first-selector does not occur until the deenergization of the release-magnet of the latter. Should the connector-shaft 202 be raised when the release-magnet is energized the release-armature 216, as above stated, pulls the double-dog under the release-link which latter catches the lug 225 and holds said double-dog out of engagement with the shaft. Said shaft then being free, for the reasons described in connection with the first-selector-shaft, returns to its normal released condition.

In Fig. 1 the first-selector D that is associated with the called line is identical with the first-selector A of the calling line and needs no explanation since like parts are

likewise represented. When reference is made to the parts of said called first-selector it will be understood that their functions and constructions are the same as those already described for the first-selector A. In connection with the selector D of the called line there are shown no bank contacts, but they have been omitted for convenience of illustration, and it is obvious that said switch is provided with bank contacts like the selector A. It will also be understood, of course, that the exchange is equipped with a plurality of subscribers' lines, each of which terminates in a selector-switch such as the selector-switch A. All such selectors are arranged in groups, and the corresponding bank contacts of all the selectors in one group are multiplied together. For example, the first contact of the first level of each switch-bank in a group are connected in multiple. Likewise, similar contacts on the rotary side are connected in multiple, and, of course, the corresponding private bank contacts are connected in multiple. This arrangement of the banks is followed throughout the exchange, not only with respect to the selector-switches, but also in connection with the connector-switches as well. In the particular system shown, of course, it is clear that there may be a multiplicity of sub-stations each of which is connected with the central station by a line of two conductors each of which lines has permanently allotted to it a first-selector. The first-selectors may be sub-divided into groups of one hundred each with all corresponding line-bank-terminals of a given group connected in multiple, a similar arrangement being followed in connection with the private-bank-terminals. For each level of first-selector line-bank-terminals one set of ten trunk-lines is provided with a conductor connected to each one of said trunks. For each level to which a first-selector-shaft may be raised its line-wipers are placed on a level with a different set of connectors for the purpose of reaching subscribers in different hundreds. Each first-selector is connected with a given set of bank-contact-points in the banks of the connectors of the given hundred to which said first-selector belongs, and when the first-selector comes into use a guarding potential is placed at the connector-private-bank-contacts of the line of the calling first-selector to prevent any calling subscriber from calling this same line. But while a line is idle a connection with said line is made over the trunk-conductors that extend between the connector-banks and the first-selector.

To fully understand the operations and events in connection with my improved arrangement a description will now be given of the apparatus and circuits brought into use in the system when one subscriber calls

another subscriber, for instance, as illustrated in Fig. 1 when the subscriber at sub-station #400 calls the subscriber at sub-station #220, which is as follows: The subscriber at the calling sub-station #400 removes his receiver from the switch-hook 2, thus causing the ground-springs 23 and 24 to come into contact and complete a circuit between the ground-terminal G^1 and the ground-post 22, through the said springs 23 and 24 and the conductors 400 and 401. Immediately after the vertical push-button 29 is then pressed twice, then the rotary-button 30 once, again the first button 29 twice, 15 and the second button 30 once, and for the last time the first button ten times, and the last button once. When the spring 33 is forced onto the ground-post 22 twice in succession for the first time, the vertical-line-conductor 402 is grounded twice, causing the vertical-line-relay 71 of the first-selector to become magnetized and thereby attract its armature 73 momentarily twice. The energizing current that passes through said vertical-line-relay at this time enters the line at the ground terminal G^1 , then passes to the ground-post 22 and through the spring 33 to the vertical-line-conductor 402; thence through the vertical-side-switch-wiper 147, conductor 403, vertical-line-relay 71, conductor 404, bridge-cut-off-relay-springs 81 and 82, conductors 405, 406 and 407 to the non-grounded terminal of battery B and to ground G. As a result the line-relay-spring 35 75 is forced onto the ground-spring 77 twice, which operation closes a second magnetizing circuit through the vertical-magnet 87. The current in this second circuit enters the line at the ground terminal G^2 and then passes through the springs 77 and 75 to the conductor 408 and through the private-springs 131 and 130 and conductor 409 to the vertical-magnet 87, passing through the conductors 410, 411, 412 and 407 to the non-grounded terminal of battery B to ground G. The vertical-magnet 87 then attracts the vertical-armature twice and raises the switch-shaft two steps. At the first step, of course, the release-link 97 is withdrawn from the double-dog 103, at which time the dog 105 engages with the circular teeth 62 and prevents the shaft from falling to its original position. As soon as the switch-shaft rises, the off-normal-spring 68 then closes with the grounded contact-point 70, at which instant, and by which act, the connector-private-bank-contacts that correspond to the line-conductors of the sub-station #400 are connected with ground, which connection establishes a guarding potential over said line #400, so that no subscriber may be able to connect with it after once the first-selector A of said line has been operated. The vertical-line-conductor being grounded twice, when the push-button 30 in turn forces the spring 34 onto the ground-post 22 once, the rotary-line-conductor 413 is grounded once. An electric current then flows through the rotary-line-relay 72 for a moment, which magnetizes the said rotary-line-relay, causing the latter to attract its armature 74 once, and to force the spring 76 against the ground-spring 77 once. As a result a second magnetizing circuit is completed through the private-magnet 126. The electric current in this latter case flows from the grounded terminal of battery B to the grounded terminal G^2 , and thence through the line-relay-springs 77 and 76 and conductors 414 and 415 to the private-magnet 126, after passing through which it then passes through the conductors 416, 412 and 407 to the non-grounded terminal of battery B and to ground G. The private-armature 125 being attracted once and restored immediately, the escapement-tooth 137 first clears the escapement-finger 142, which latter then falls against the second tooth 435; and when the armature returns to its normal position this latter tooth also clears in turn the said escapement-finger. At that instant the side-switch is drawn into the second position by the retracting-spring 143 with the cam-lug 144 resting against the cam 58. It will be understood that the 95 prongs of the bifurcated end of the link 164 that rests upon the T-shaped extremity of the double-dog releasing-arm 108 are of sufficient length to permit the said releasing-arm 108 to move from the position that it 100 holds when the double-dog is held normally locked by the release-link 97 to the position it assumes when the said double-dog is released and, therefore, without disengaging said prongs. At the moment that the side-switch passes from the first to second position another circuit is completed through the rotary-magnet 112, when the side-switch-wiper 145 closes with the contact-point 155. The current then flows from the ground terminal G^2 to the contact-point 155 and through the side-switch-wiper 145 and conductor 417 to the rotary-magnet-coil 114, thence through the interrupter-springs 122 and 123 and through the second rotary-magnet-coil 113 to the conductors 411, 412 and 407 and to the non-grounded terminal of battery B and to ground G. The rotary-magnet 112 then attracts the rotary-armature 115 and forces the rotary-pawl 119 into engagement with one of the longitudinal teeth 61, causing the shaft to rotate one step, since said shaft has already been raised. Just at the time, or at the instant before 125 the rotary-armature strikes the rotary-magnet pole-pieces, the rotary-dog 106 falls behind the first of the longitudinal teeth, in the manner already described, to prevent the shaft from returning to its normal pos- 130

tion when the rotary-magnet becomes de-energized at the instant that the interrupter-finger forces the interrupter-springs apart and destroys the energizing circuit through the said magnet. This interruption occurs just at the time when the rotary-armature strikes the pole-pieces. At the same time that the rotary-pawl 119 advances to engage the longitudinal teeth, as 10 described, the rotary-armature-finger comes into contact with the private-armature 125, producing a depression of the latter at the same time that the rotary-pawl produces a rotation of the shaft. As the shaft begins 15 to rotate the cam 58 very soon passes out of reach of the cam-lug 144 and permits the escapement-finger 142 to fall against the tooth 138 before the rotary-armature-finger 124 has depressed the private-armature 125 20 too far. Very soon, however, the said tooth 138 is carried below the finger 142, which latter then falls against the upper tooth 136 at about the time that the shaft-wipers are rotated onto the first contact of the second 25 level of their respective banks. As soon as the energizing circuit through the rotary-magnet is interrupted the rotary-armature then begins to return to its normal position, and the private-armature 125 as well, following up the receding movement of the rotary-armature-finger 125. Very soon the tooth 136 clears the escapement-finger 142 and the side-switch springs into third position with the escapement-finger 142 against 30 the side-switch-stop 150. The shifting of the side-switch takes place just before the interrupter-finger permits the interrupter-springs 122 and 123 to reengage so that by 35 the time that they do reengage the energizing circuit that has been described through the rotary-magnet has been destroyed between the side-switch-wiper 145 and the contact-point 155. When the motion of the rotary-armature ceases permanently the 40 operation of the first-selector comes to an end, the line-wipers 55 and 56 having seized upon an idle trunk-line similar to the trunk-line whose conductors 418 and 419 terminate at the tenth set of contacts of the second 45 level of the same line-bank. The seized line is protected from further seizure by a guarding potential at the private-wiper and, therefore, at the first contact of the second level of the private-bank 52 and to all 50 other private-contacts in multiple. Said guarding potential is established by reason of the connection between the grounded terminal of battery B and said private-contacts through the ground terminal G⁴, side- 55 switch-wiper 146, conductor 420, back-release-relay 83, conductor 421, and the private-wiper 57. Similarly, should any first-selector appropriate to its use the second trunk-line of the same level, a guarding potential will appear at the second private- 60

contact of the second level of the private-bank 52, as well as of all other private-banks in multiple. And should a third first-selector seize the third trunk on the same level a guarding potential will also appear at the third private-contact of the second level, and should the fourth, fifth, etc., and ninth trunks be occupied guarding potentials would be found at the fourth, fifth, etc., as well as at the ninth private-contact- 70 terminals of the second level of the private-bank. Therefore, if the first nine trunk-lines of the second level are busy a guarding potential is found at each one of the first nine private-contacts of the second level of 75 the private-bank 52. If this condition exists at the time that the calling subscriber grounds his rotary-line-conductor by pressing button 30, the rotation of the shaft will not terminate as soon as the wipers have 80 moved onto the first terminal of the level to which they have been raised. 85

The first nine private-contacts being grounded, then when the calling subscriber grounds the rotary side of the line the side-switch trips into second position in the manner described; but then the rotation of the shaft will begin, not to cease, until the wipers have been carried beyond the last of the busy trunk-lines, in this case 90 onto the tenth terminal of the second level of the banks in question. This operation takes place in the following manner: The energizing circuit through the rotary-magnet being closed, as was pointed out, at the 95 juncture when the side-switch-wiper 145 engages with the contact-point 155, the rotary-armature is attracted by the rotary-magnet 112, and the shaft is rotated one 100 step in the manner described, so that the 105 line and private wipers are rotated into engagement with the first terminal of the second level of their respective banks. At the same time the private-armature is depressed by the rotary-armature-finger and 110 the interrupter-springs 122 and 123 at the end of the stroke are separated by the interrupter-finger 121. There being a guarding potential at the first contact which the private-wiper meets, a circuit is completed 115 through the private-magnet 126, which extends from the grounded terminal of the battery B through the private-wiper of whatever first-selector is occupying the first trunk of the second level in question, through the bank-multiplying-conductors to the contact-point with which the private-wiper 57 has engaged, hence through said private-wiper, conductor 421, winding of the back-release-relay 83, conductor 420, the 120 side-switch-wiper 146, contact-point 156, conductors 422 and 415 and private-magnet 126, to the non-grounded terminal of battery B and to ground G. The private-armature 125 is thereby retained in the depressed condi- 130

tion, even after the energizing circuit is broken at the interrupter-springs, and while the rotary-armature-finger 142 returns to its normal position in response to the reTRACTING tension of the rotary-armature-spring 117, since the escapement-finger 142 is held prisoner by the upper foremost escapement-tooth 136. The side-switch-wiper 145 being, therefore, retained in engagement 5 with the grounded contact-point 155, as soon as the interrupter-springs reengage the energizing circuit through the rotary-magnet 112 is completed once more. As a result, the rotary-armature is attracted again, 10 the shaft is rotated one more step, and the private-wiper 57 is moved onto the second terminal of the second level of the private-bank 52. Said second contact also being grounded the energizing circuit through 15 the private-magnet is still maintained, so that still the side-switch is not liberated when the rotary-armature again returns to its normal position. Clearly, then, the shaft will be rotated in a step-by-step manner as 20 long as the private-wiper continues to meet with grounded private-contacts. After having rotated onto the ninth contact, the private-wiper is rotated one more step into engagement with the tenth contact of the 25 second level of the private-bank; but this last contact being devoid of guarding potential, as soon as the said wiper leaves the ninth contact the magnetizing circuit through the private-magnet that has, up to 30 this time, maintained the private-magnet energized is broken. This occurs at just about the time when the rotary-armature is at the end of its forward stroke, so that the private-armature that has, up to this 35 time, held the side-switch in its second position, by the magnetizing force that has now disappeared from the private-magnet, falls back upon the rotary-armature-finger and follows said finger as the rotary-armature 40 returns to its normal position.

Between the time that the private-armature is released by the private-magnet and the time that the rotary-armature fully regains its normal position, the escapement-finger 142 which, during the rotation of the shaft, has been resting against the foremost tooth of the upper escapement-spring, disengages from said tooth and permits the side-switch to pass to the third position. It 50 is then that the side-switch-wiper 145 leaves the contact-point 155 and passes onto the contact-point 159. This disengagement occurs just before the interrupter-springs 122 and 123 reengage, so that the circuit through 55 the rotary-magnet is permanently broken in order that no further rotation of the shaft may take place during its operation. The side-switch-wipers 147 and 148 having engaged with the contact-points 161 and 162, 60 the subscriber's line-conductors 402 and 413 are thereby extended through the respective wipers and over the conductors 423 and 424 to the vertical and rotary line-wipers 55 and 56, respectively. Said wipers, being at the time in engagement with the tenth contact 70 of the second level of the line-bank, place the calling subscriber in connection with the connector C through the vertical and rotary trunk-conductors 418 and 419. The calling line being thus extended, when the subscriber presses the vertical-button 29 twice for the second digit he again grounds the vertical-line-conductor 402 twice and thus operates the vertical-line-relay 273 of the connector C twice. The path that the current takes from the ground terminal G¹, in this case, after leaving the ground-post 22 and passing over the vertical-line-conductor 402 to the vertical-line-side-switch-wiper 147 then passes through the conductor 423, vertical-wiper 55, vertical-trunk-conductor 408, vertical-line-relay 273, winding 300 of the differential-relay 298, conductors 425 and 426 to the non-grounded terminal of battery B to ground G. The vertical-line-relay of 80 the connector attracts its armature twice and the latter thereby forces the line-relay-spring 275 twice against the grounded spring 276. As a result, the vertical-magnet 211 is energized twice in succession, 85 raising the conductor-shaft 202 one step at each time by means of the vertical-armature 304 and the vertical-pawl 213. The current through said vertical-magnet passes from the ground terminal G¹ through springs 276 and 275, conductor 425^a, private-springs 242 and 241, conductors 426^a and 427, vertical-magnet 211, conductor 428, side-switch-wiper 253, conductors 429, 430 and 426 to the non-grounded terminal of battery B and to ground G. It has been pointed out that at the first movement of the vertical-arm 100 212 the release-link 220 is disengaged from the double-dog 219 by the L-shaped piece 214, and that the vertical-pawl 213 engages one of the circular teeth, raising the shaft so that the vertical-dog 222 catches the said shaft in a raised position, in the same manner described in connection with the first-selector. At the second operation of the 105 vertical-armature the shaft is raised another step, in which new position it is still retained by the same vertical-dog 222. The calling subscriber next presses the rotary-button 30 once, grounding the rotary-line-conductor 413 as above, and causing thereby an energizing current to flow through the rotary-line-relay 279 of the connector C for a moment. This current flows from the ground terminal G¹, at the sub-station 110 #400, to the ground-post 22, thence over the rotary-line-conductor 413 and through the first-selector side-switch-wiper 148, contact-point 162, conductor 424 to the rotary-line-wiper 56, thence over the rotary-trunk-con- 115 120 125 130 135

ductor 419 and through the rotary-line-relay 279 through the winding 299 of the differential-relay 298, through the conductor 431 and ringer-relay-springs 290 and 291 to the conductors 430 and 426 to the non-ground terminal of battery B and to ground G. The rotary-line-relay, being thus magnetized once, has its armature 280 attracted once, which forces the springs 281 and 276 into contact. As a result, the connector-private-magnet 232 is energized, a current through which flows from ground G⁵ through the springs 276 and 281, conductor 432, private-magnet 232, conductors 433, 434 and 431, ringer-relay-springs 290 and 291, conductors 430 and 426 to the non-grounded terminal of battery B and to ground G. The private-magnet being energized for the first time, the escapement-finger 246 clears the escapement-tooth 237 at the downward stroke of the armature 233, and clears the upper escapement-tooth 236 at the return stroke. The side-switch, of course, is brought into second position and stops there as the lug 247 strikes the cam 206; and the side-switch-wiper 253 having then left the contact-point 258 is in engagement with the contact-point 263 instead, so that when the subscriber next presses the vertical-button 29 ten times and energizes the vertical-line-relay 273 ten times, the rotary-magnet 228, instead of the vertical-magnet 211, is magnetized ten times. The energizing circuit through this latter magnet permits the current to flow from the ground terminal G⁵ through the springs 276 and 275, as explained, and then the private-springs 242 and 241, after leaving which it passes through conductor 426^a and the rotary-magnet 228, and passes over the conductor 435 to the contact-point 263, side-switch-wiper 253, thence to the non-grounded terminal of battery B and to ground G. The rotary-armature 229 is then attracted ten times—that is, once each time that the rotary-magnet is magnetized. Each time that it is attracted, the rotary-pawl 231 engages with one of the longitudinal teeth 207 and rotates the shaft 202 one step in the same way that the first-selector-rotary-magnet rotates the first-selector-shaft.

At the first rotary step the shaft-rest 305 receives the shaft 202, when the vertical-dog 222 is drawn out of engagement with the circular teeth at just about the time when the rotary-dog 223 reaches the crest of the longitudinal tooth over which it has to pass at the time; and by the time that the rotary-armature strikes the rotary-magnet 60 pole-pieces this latter rotary-dog drops into locking engagement behind the said longitudinal tooth and retains the shaft in its advanced rotary position. At the first rotary step the shaft-wipers, of course, pass onto the first contact of the second level of their

respective banks; at the second step onto the second contact, and so on step-by-step until they reach the tenth contact of their respective banks. The last step of the calling subscriber in completing his connection is to again ground the rotary-line-conductor 413 once by pressing the rotary-button 30 once. Again the rotary-line-relay 279 is energized and again the private-magnet 232 attracts its armature 233 once. The shaft having 70 been rotated so that the cam 206 no longer forms an obstruction to the side-switch-arm 245, at the downward stroke of the private-armature the escapement-finger 246 clears the tooth 239, and when said armature returns toward its normal position the upper tooth 238 is also cleared, at which instant the said side-switch springs into third position. The passage of the side-switch-wiper 255 to the third position connects the private-wiper 205 with the ground terminal G⁶, when the said side-switch 255 passes onto the contact-point 270. This connection establishes a guarding potential at the tenth private-contact of the second level of the 80 private-bank 201 that corresponds to the terminal of the normal-conductors 436 and 437 of the called subscriber #220, so that no other subscriber may call in upon said line while said guarding potential exists. It will 90 be understood, of course, that the same guarding potential exists at all other private-bank-contacts in multiple with the private-bank-contact mentioned. The calling first-selector, it will be remembered, places a guarding potential at the private-banks of the connectors of the hundred to which the subscriber #100 belongs at points corresponding to the line #100 at the instant that the off-normal-spring 68 comes into 10 contact with the grounded spring 70. Said guarding potential, by extending to the connector-banks over the private-normal-conductor 438, prevents calling subscribers from 100 entering into communication with the calling line over the normal-trunk-conductors 439 and 440; and the calling connector, as soon as the side-switch passes to third position, provides a guarding potential at the private-bank-contact that corresponds to the 110 line-terminal of the called line, so that no other calling subscriber may interfere with the completed connection. In this way both parties, the called and the calling, are rendered safe against interference while the two 120 lines are busy. The establishment of a guarding potential at the tenth contact of the second level of the private-bank 201 not only protects the called line from further seizure, but at the same time forces a current through the bridge-cut-off-relay 350 of the called first-selector, which relay, by its armature 351, controls the bridge-cut-off-relay-springs 352, 353 and 354. This latter relay, when magnetized, separates the said 130

springs from each other and thereby opens up a bridge circuit normally established through the vertical and rotary line-relays 355 and 356 across line-conductors 441 and 442, and at the same time interrupts a connection between said relays and the non-grounded terminal of battery B, which terminal is directly connected with the spring 354. Since the conductors 441 and 442 are included, one on each side of the main talking circuit, as will be hereinafter disclosed, it is desirable to remove all unnecessary bridged connections from between them, for obvious and other reasons, to obtain the best results.

The energizing circuit through the bridge-cut-off-relay 350 extends from the ground terminal G^e to the connector-side-switch-contact-point 270, side-switch-wiper 255, conductor 443, private-wiper 205, trunk-conductor 444, spring 357, contact-point 358, bridge-cut-off-relay 350 to the non-grounded terminal of battery B and to ground G. When the side-switch-wiper 255 passes into contact with the grounded contact-point 270, still another circuit is then formed through the ringer-relay 287, which energizes the said relay. The current in this circuit passes from the same ground terminal G^e to the side-switch-wiper 255, conductor 447, ringer-relay 287, conductor 446, differential-relay-springs 302 and 303, conductor 447, contact-point 268, side-switch-wiper 253, the non-grounded terminal of battery B to ground G. This relay 287 at once attracts its armature and forces the ringer-relay-springs 290, 293 and 296 away from corresponding ringer-relay-springs 291, 294 and 297, respectively, and into contact with other ringer-relay-springs 289, 292, and 295, respectively. The circuits through the vertical and rotary line-relays 273 and 279, respectively, each time that the vertical and rotary push-buttons 29 and 30 have been pressed, have comprised in the one case the winding 300 of the differential-coil 298, and in the other case the winding 299 of said coil. Therefore, in each case the armature 301 of said relay has been attracted; but at this particular stage the energization of this relay has no significance. Said windings of the differential-coil are so wound that when a current flows through them in series the relay will not energize, but when current is sent through one winding only, or through both windings in multiple, the said relay will energize. It should be observed that the ringer-generator E is connected directly to the ringer-relay-springs 294 and 297, and that said springs are respectively normally engaged with the springs 293 and 296. Therefore, when the side-switch is in the third position, if the ringer-relay were not energized ringing current would pass out over the called subscriber's line-conductors

by way of the normal-line-conductors 436 and 437, since the vertical and rotary side-switch-wipers 256 and 257 are then directly connected with the line-wipers 203 and 204, respectively. It is for this reason that special provision has been made for the ringer-relay-springs 293 and 296 to separate from the ringer-relay-springs 294 and 297 at the instant that the connector-side-switch passes into third position. The connection between the calling and called lines having been established, the calling party is now in a position to signal the called line by means of his signaling-button 12. But before going any farther it will be explained that if for any reason the called line is busy at the time that the calling subscriber grounds his rotary line-conductor for the last time, to transfer the connector-side-switch from second to third position, because of a guarding potential, the calling connector is thereby released. For instance, if the called line #220 had been called by another connector before the connector C there would have been a guarding potential at the tenth private-contact of the second level of the private-bank 201, corresponding to the line of the sub-station #220. Or, on the other hand, had the shaft of the first-selector D of the called line been out of its normal position because of the operation of said shaft by the subscriber at the sub-station #220, or for any other reason, the same private-bank-contact would have been connected to ground from the instant that the normal-post-arm 359 permits the off-normal-spring 357 to engage in contact with the grounded contact-point 360. Said guarding potential, in this last case, would reach the connector-private-bank by way of the private-normal-conductor 444. At any rate, should the private-wiper 205 find such a guarding potential at the instant that the calling subscriber grounds his rotary-line-conductor 413, for the last time, the connector would be released and would not complete the circuit between the calling line and the desired line. This release occurs because of the energization of the release-magnet 215, under such conditions, and while the side-switch is in its second position, which position is the proper one for the side-switch before the last grounding of the rotary side of the line. The private-wiper 205 finding a guarding potential at the instant that the calling subscriber grounds the rotary-line 413, by pressing the rotary-button 30 for the last time, the connector is thereby released, and the subscriber fails to make the desired connection. The release occurs because of the energization of the release-magnet at the instant that the private-armature 233 closes the private-springs 243 and 244 as a result of the energizing of the rotary-line-relay 279.

The energizing circuit through the release-

magnet permits the current to flow from the grounded terminal of batter B to the tenth contact of the second level of the private-bank, thence through the private-wiper 205 to the side-switch-wiper 255, contact-point 265, conductor 448, and through the private-springs 243 and 244, conductors 449 and 450 to the release-magnet 215 after passing through which it flows through the conductors 451, 434 and 431, ringer-relay-springs 290 and 291, conductors 430 and 426 to the non-grounded terminal of battery B and to ground G. The connector-release-magnet being energized, the release-armature 216 moves the double-dog 219 in such manner that the lug 225 is caught and held in the aperture 227 on the end of said link. Of course, when the double-dog is thus rotated the locking-arm 223 is withdrawn from the longitudinal teeth, and the shaft is then free to rotate toward its normal rotary position, owing to the tension in the coiled spring 210, until the normal-post-arm 209 strikes the normal-post 306. At that instant the shaft-support 305 enters the slot 307, and the said shaft of necessity falls to its normal position. The release-armature, upon rotating the double-dog 219, at the same time drives the side-switch to its first position by means of the side-switch-link 252 and the double-dog release-arm 224. This latter, by pressing the former back, forces the escape-finger 246 back between the escape-movement-springs 234 and 235, and is caught behind the rearmost lower tooth 237, behind which it is retained until the connector comes into use again. The restoration of the connector-shaft may take place even while the release-magnet 215 is energized; but since the energizing circuit through said magnet comprises the private-wiper 205, and also the side-switch-wiper 255, it will be evident that as soon as the shaft begins to rotate to its normal position the energizing circuit will be broken as soon as the private-wiper 205 leaves the private-contact-point with which it has been engaged. The same energizing circuit is also interrupted at the side-switch-wiper 255 when the latter is forced back into its first position. The calling subscriber, thinking he has established connection, presses the signaling-button 12 at the sub-station #400, with the result that the spring 11 is separated from the contact-point 10 and closed into connection with the grounded contact-point 35. The said spring 11 being in direct connection with the vertical-line-conductor 402, through the primary circuit-springs 13 and 14, and through the contact-point 31 and spring 33, this act grounds the said vertical side of the line as long as the push-button 12 is depressed and magnetizes the vertical-line-relay of the connector; and since the side-switch-wiper 255 of the connector has been restored into con-

nection with the contact-point 258, the vertical-magnet 211 is energized also. As a result, and for reasons previously described, the shaft of the connector is raised and the spring 308 is brought into contact with the contact-point 309. The engagement of these two parts completes a circuit over which a busy signaling circuit, provided by any suitable means represented at F, Fig. 1, is sent over the line to the calling subscriber's station and through his receiver. Said busy signal will notify him that the desired line is busy. This busy current that is generated in a suitable coil 311 passes from thence to the conductor 452 through the side-switch-wiper 254, contact-point 259, conductor 453, springs 308 and 309, conductors 454 and 455, condenser 456, rotary-trunk-conductor 419, rotary-wiper 56 of the first-selector A, conductor 424, contact-point 162, side-switch-wiper 148, rotary-line-conductor 413, primary winding 7, transmitter 9, contact-point 10, springs 11, 13 and 14, vertical-line-conductor 402, side-switch-wiper 147, contact-point 161, conductor 423, vertical-line-wiper 55, vertical-trunk-conductor 418, vertical-line-relay 273, winding 300 of the differential-coil 298, back to the coil 311. The subscriber then restores his receiver to its hook, thereby grounding both line-conductors 402 and 413 at once. The grounding occurs when the release-cam 3 forces the release-springs 25, 26 and 27 into contact. The grounding of the rotary-line-conductor 413, in this case, energizes the rotary-line-relay 279 of the connector in the usual way. The connection from said conductor to the ground G¹ is completed from said ground through the springs 24 and 23, conductor 400, through the release-springs 27 and 26, to the conductor 413. The energizing of the rotary-line-relay forces the release-spring 278 toward the spring 277; at the same time, the grounding of the vertical-line-conductor 402 through the release-springs 25, 26 and 27 energizes the vertical-line-relay 273, which latter then forces the spring 277 against the spring 278. The contact of these two springs establishes a circuit which conveys a current through the release-magnet of the connector and through the back-release-relay 83 of the first-selector. The circuit begins with the grounded terminal G⁴ of the first-selector-side-switch and extends through the contact-point 160, side-switch-wiper 146, conductor 420, back-release-relay 83, conductor 421, private-wiper 57, release-trunk-conductor 474, springs 277 and 278, conductor 450, release-magnet 215, conductors 434 and 431, ringer-relay-springs 290 and 291, conductor 426, to the non-grounded terminal of battery B and to ground G. The release-magnet becoming magnetized the restoration of the connector results in the usual manner.

The back-release-relay 83 becoming energized at the same time forces the back-release-relay-springs 85 and 86 into contact, which closes an energizing circuit through 5 the release-magnet 111, of the first-selector. The circuit in this last case extends from the grounded terminal G⁷, through the springs 85 and 86, release-magnet 111, to the non-grounded terminal of battery B and 10 to ground G. Thus the release-magnet of the first-selector attracts its armature 99, and at the instant that the energizing circuit is destroyed through the back-release-relay, when the release-springs at the sub- 15 station #400 are permitted to separate, the circuit through the release-magnet 111 also is destroyed, and the release-armature 99 returns to its normal position, restoring the first-selector in the well-known manner. At 20 the same time, the release-armature of the connector-release-magnet 215 returns to its normal position, leaving the connector in a full normal condition. But it has been described that the subscriber did not find the 25 line busy, and that having made a connection he was in a position to signal the called subscriber. After doing so, he presses his signaling-button 12 in a manner already stated, and thereby grounds the vertical- 30 line-conductor 402. But as soon as the spring 11 reaches the contact-point 35 the grounding of the vertical-line energizes the vertical-line-relay 273 and the differential-relay 298, since the current in this case 35 passes only through the winding 300 and thence to the non-grounded terminal of the battery B. As soon as the differential-relay attracts its armature 301, the differential-relay-spring 303 is forced away from the 40 spring 302, and as a result the magnetizing current through the ringer-relay, which has been described, is interrupted at that point. The ringer-relay becoming deenergized, the springs 293 and 296 then fall back into contact with the ringer-generator-springs 294 and 297, respectively. As a result, ringing current is projected out on the line of the called subscriber, which current passes through his ringer for the purpose of signaling him. This current passes from the 45 generator E to the conductor 458, springs 297 and 296, side-switch-wiper 257, contact-point 272, conductor 459, rotary-line-wiper 204, rotary-normal-conductor 437, conductor 442, spring 375, contact-point 376, conductor 460, ringer-circuit-springs 377 and 378, ringer and condenser 379 and 380, respectively, conductor 461, contact-point 381, spring 382, vertical-line-conductor 441, vertical-normal-conductor 436, vertical-wiper 403, conductor 462, contact-point 271, side-switch-wiper 256, springs 293 and 294, conductor 463, back to the generator E. As 50 soon as the calling subscriber releases his signaling-button the current through the

differential-relay 298, of course, is interrupted. The differential-relay becoming deenergized, the springs 302 and 303 that it controls, upon reengaging, reestablish the energizing current through the ringer-relay 79 287, which latter, upon attracting its armature, severs the connection between the generator E and the called line. As the called subscriber removes his receiver 383 from the switch-hook 384, the latter, upon rising, 75 destroys the ringing circuit through the ringer 379 at the instant that it permits the springs 377 and 378 to separate. It also forces the primary circuit-springs 385 and 386 into contact, closing a circuit through 80 its own station that provides the transmitter 387 and primary winding 388 of the induction-coil 389 with current for inter-communicating purposes. The current enters into this circuit from the ground terminal G⁶, thence to the contact-point 270 and side-switch-wiper 255, conductor 465, back-bridge-relay 282, ringer-relay-springs 295 and 296, side-switch-wiper 357, contact-point 272, rotary-line-wiper 204, normal-conductor 437, line-conductor 442, primary winding 388, transmitter 387, through the primary circuit-springs 385 and 386 to the vertical-line-conductor 441, vertical-normal-conductor 436, vertical-line-wiper 203, contact-point 271, side-switch-wiper 256, ringer-relay-springs 293 and 292, retardation-coil 283, to the non-grounded terminal of battery B and to ground G. 95

The energizing current for the talking 100 circuit, in passing through the back-bridge-relay-coil 282, energizes said coil and causes the armature 284 to close the back-bridge-relay-springs 285 and 286 together. At the instant that these two springs 285 and 286 105 come into contact the calling sub-station is provided with current for talking purposes. The current in this circuit passes from the non-grounded terminal of battery B through the conductors 426 and 425, winding 300 of 110 the differential-relay-coil 298, vertical-line-relay 273, vertical-trunk-conductor 418, vertical-wiper 55 of the first-selector A, conductor 423, contact-point 161, side-switch-wiper 147, vertical-line-conductor 402, spring 33, contact-point 31, conductors 466 and 467, primary circuit-springs 14 and 13, spring 11, contact-point 10, transmitter 9, primary winding 7 of the induction-coil 8, conductors 468 and 469, contact-point 32, 115 spring 34, rotary-line-conductor 413, side-switch-wiper 148, contact-point 162, conductor 424, rotary-line-wiper 56, rotary-trunk-conductor 419, rotary-line-relay 279, winding 299 of the differential-relay 298, 120 conductor 431, ringer-relay-springs 290 and 289, conductor 470, back-bridge-relay-springs 285 and 286, conductor 465, side-switch-wiper 255, to the ground terminal G⁶. 125 It will be noticed that the two windings 299 130

- and 300 of the differential-coil 298 are included in the circuit that provides the calling subscriber with the current for talking purposes. This current, since it passes through the windings of the differential-relay in series, does not energize said relay. Since the talking circuit current to the calling station passes to the main line-conductors 418 and 419 through the vertical and rotary line-relays 273 and 279, these two relays, as soon as said circuit is established, become magnetized and attract their respective armatures 274 and 280. This being the case the release-springs 277 and 278, which are under the control of said line-relays, are brought into connection, and the connector would be released were it not for the fact that the connection between the release-magnet 215 and the non-grounded terminal of the battery B is interrupted between the ringer-relay-springs 290 and 291, while the ringer-relay 287 is energized. Under these conditions, the primary windings 7 and 388 of the sub-stations #400 and #220, respectively, are connected in series in a circuit through the condensers 456 and 471. Said circuit comprises in series the primary winding 7, transmitter 9 of the sub-station #400, the primary circuit-springs 13 and 14, vertical-line-conductor 402, first-selector-side-switch-wiper 147, line-wiper 55, trunk-conductor 418, condenser 471 of the connector C, the conductor 472, ringing-relay-springs 292 and 293, side-switch-wiper 256, line-wiper 203, normal-conductor 436, vertical-line-conductor 441, primary circuit-springs 386 and 385 of the sub-station #220, transmitter 387, primary winding 388, rotary-line-conductor 442, rotary-normal-conductor 437, line-wiper 204, side-switch-wiper 257, ringing-relay-springs 296 and 295, conductors 473, 455, condenser 456, trunk-conductor 419, rotary-line-wiper 56, side-switch-wiper 148, rotary-line-conductor 413, and back to the primary winding 7. The receivers 16 and 383 of the two sub-stations in question are in series each in a local circuit with their respective secondary windings 17 and 390 of their induction-coils 8 and 389, and in a very well-known and familiar manner the two subscribers may communicate with each other, since their primary circuits are charged with a suitable current from the central or common battery B. The connection between the two subscribers having been established, it may then be destroyed or opened from the calling sub-station, by the simultaneous grounding of the vertical and rotary line-conductors. Should the subscriber at sub-station #400 restore his receiver the release-springs 25, 26 and 27, coming into contact, would place the vertical and rotary line-conductors 402 and 413 in connection with ground at the grounded terminal G¹. The grounding of the rotary-line-conductor produces a cessation of the flow of current through the rotary-line-relay 279 and the winding 299 of the differential-relay 298. This is brought about by the short-circuiting of these two relays in series through ground. This short-circuit, beginning with ground G¹, extends through the ground-springs 24 and 23 to the release-spring 27 and thence through the release-spring 26 to the rotary-line-conductor 413, through the side-switch-wiper 148 of the first-selector A, rotary-line-wiper 56, conductor 419, rotary line-relay 279, winding 299 of the differential-relay 298, conductor 431, ringer-relay-springs 290 and 289, conductor 470, back-bridge-relay-springs 285 and 286, conductor 465, side-switch-wiper 255 to the ground terminal G². The rotary-line-relay becomes deenergized, and the release-spring 278 recedes from the release-spring 277; and since only the winding 300 of the differential-relay 298 is receiving any current, said relay 298 becomes magnetized. The current-flow through said relay extends from ground G¹ to the release-springs 27, 26 and 25 to the vertical-line-conductor 402, side-switch-wiper 147, conductor 423, line-wiper 55, conductor 418, vertical-line-relay 273, differential-winding 300, to the non-grounded terminal of battery B and to ground G.
- The energization of the differential-relay, as above, produces a deenergization of the ringer-relay 287 which, upon restoring its armature to normal position, permits the ringer-relay-spring 290 to separate from the spring 289, and to return into engagement with the spring 291. The engagement of these last two ringer-relay-springs 290 and 291 establishes an energizing circuit again through the second differential-winding 299 of the differential-relay 298, and current in this way passes through said coil in such a direction as to reinforce the winding 300; and, therefore, even after the ringer-relay becomes deenergized, the differential-relay continues to remain energized as long as the release-springs 25, 26 and 27 remain in contact. The magnetizing current through the last differential-coil in question passes from the ground terminal G¹ to the rotary-line-conductor 413, thence through the rotary-line-relay of the connector and differential-winding 299, ringer-relay-springs 290 and 291 to the non-grounded terminal of battery B to ground G. Furthermore, at the instant that said ringer-relay-springs resume their normal engagement, and simultaneous with the reenergization of the rotary-line-relay 279 of the connector, the release-springs 277 and 278 under the control of the line-relays of said connector are forced into engagement once more, since both said relays are

energized at the time. The engagement of said springs, in the manner already pointed out, produces the energization of the release apparatus of the connector and first-selector, 5 releasing said switches. It will be clear that as soon as the connector-private-wiper disengages from the private-contact-point with which it has been in engagement, the bridge-cut-off-relay 350 of the first-selector D is 10 then restored to its normal position, with the springs 352, 353 and 354 in contact, leaving the said first-selector in a condition to be operated by the sub-station #220. At 15 the same time that the private-wiper leaves its contact-point the line-wipers 203 and 204 also leave their contact-points, and as a result the circuit conveying energizing current for talking purposes to the sub-station #220 is also destroyed, causing 20 at the same time the deenergization of the back-bridge-relay 282. This relay as soon as deenergized permits the springs 285 and 286 to resume their normal position; their separation produces no effect, 25 since their influence is destroyed as soon as the ringer-spring 290 separates from the ringer-relay-spring 289. Had the subscriber at sub-station #220 restored his receiver 383 to the switch-hook 384 before the connection 30 was destroyed between the two sub-stations, the separation of the primary circuit-springs 385 and 386 that would have resulted would have then caused the cessation of the flow of current to the sub-stations for talking 35 purposes. This is evident, because as pointed out the circuit providing current at the sub-station #400 is controlled by the back-bridge-relay-springs 285 and 286. Said back-bridge-relay is in turn under the control 40 of the called subscriber and in series with the primary circuit-springs 385 and 386; therefore, when said springs are permitted to separate, the circuit through the back-bridge-relay is destroyed, and as a result 45 of the current that flows to the sub-station #400 is interrupted, which current, as has been pointed out, flows only when the springs 285 and 286 are in contact. It has been found in practice that good results are 50 obtained when the connector-line-relays 279 and 273 are wound to a resistance of 125 ohms each, in series with the windings 299 and 300 of the differential-relay 298 of 250 ohms each. Also the back-bridge-relay 282 55 and back-bridge-retardation-coil 283 may be wound to a resistance of 375 ohms each. Thus it will be seen that in the arrangement of circuits, to obtain the foregoing results, the private wiper 205 is connected in multiple with the ringer relay 287, which relay therefore energizes when the side switch passes to third position and remains energized during talking. Again, the busy-release-circuit—that is to say, the circuit by 60 which the connector is automatically released when an attempt is made to set it on a busy line—includes contacts of the ringer-relay, these contacts being normally closed. Furthermore, it will be seen that this private-wiper 205 is also employed for establishing a guarding potential for any called line with which the connector makes connection, and is combined not only with the said ringer-relay, but also with the double-wound relay having the coils 299 and 300, 65 substantially as shown and described. 70

With the arrangement shown, the back-bridge-relay 282 of the connector is connected to the rotary-line-conductor at a point between the condenser 456 and the ringer-relay springs, the circuit of this back-bridge-relay including four springs of the ringer-relay. Again, it will be seen that the said private-wiper, which is new in a connector of this kind, gets current from the same 80 ground that gives current to the coil of the ringer-relay, namely the ground G^o extending from the third contact 270 of the side-switch. In addition, it will be seen that the upper ringer-relay spring 289 is connected 85 directly with the spring 285 of the back-bridge-relay 282, so that the called subscriber can control the supply of current to both lines for talking purposes, thus insuring against any undesirable waste of current. 90 In other words, no current for talking purposes is flowing through the calling subscriber's line until after the called subscriber answers. It will also be seen that the back-bridge-relay is so connected as to enable the 95 called subscriber to put talking current on both lines through contacts of the ringer-relay. Another feature consists in the said private-wiper 255 of the side-switch, which wiper is connected with the shaft private-wiper 205, the ringer-relay-coil 287, the back-bridge-relay-coil 282, and the spring 285 of the back-bridge-relay. Furthermore, the side-switch private-wiper second contact is only connected with the normally-open 100 spring of the private-magnet, and arranged in combination with the new connections for 105 the side-switch private-wiper. 110

In connection with the subscriber's sub-station apparatus, it will be seen that the receiver has a circuit which is totally independent of the main line-circuit, inasmuch as the receiver is only inductively connected with the main line-circuit. With this arrangement, the ringing-key is in the circuit 115 of the transmitter, but not in the circuit of the receiver. With this arrangement of the subscriber's apparatus, the construction is 120 very much simplified, and I find that better results are obtained in various ways. 125

With further respect to the exchange apparatus, I believe I am the first to provide a ringing-relay which is energized continu-

ously and necessarily during conversation between two automatic telephone exchange subscribers, in order to maintain the continuity of the talking circuit, and in a commercially successful system.

5 It is obvious that the resistance of the various coils, relays and magnets can be adjusted and changed to suit the conditions of any particular case, and without departing from the spirit of my invention.

10 It will be understood that the selectors herein described and illustrated can be of the general type disclosed in Patent No. 815,321, granted March 13, 1906, to Keith, Erickson

15 and Erickson. It will also be understood that the connectors herein referred to can be of the general type disclosed in Patent No. 815,176, granted March 13, 1906, to Keith, Erickson and Erickson.

20 What I claim as my invention is:—

1. A telephone exchange connector provided with a line-conductor, a condenser in said conductor, a ringer-relay having a normally open spring in which said conductor 25 terminates, and a back-bridge-relay having one terminal connected with said line-conductor at a point between the said condenser and the said spring, together with means controlled by said back-bridge-relay, and 30 under the exclusive control of any called subscriber, for supplying current for talking purposes to the calling line.

2. A telephone exchange connector provided with line-circuit-conductors each having a condenser therein, and a back-bridge-relay located on the side of the condensers toward the called subscriber and adapted to be controlled exclusively by the latter, means dependent upon the energization of 35 said relay for supplying talking current to the calling line, and a ringer-relay having at least four normally open switch-springs, together with an energizing circuit for said back-bridge-relay, said energizing circuit 40 including said springs.

3. A common battery automatic telephone exchange connector provided with a differential relay and with a private wiper, together with private bank contacts adapted 45 to be engaged by said private wiper, a second relay and means for energizing it over a local circuit during talking, one relay controlling the other, connections between the second relay contacts and said 50 private wiper, and means whereby the private wiper prevents connection of the contacts of the energized relay with a busy line.

4. A common battery automatic telephone 55 exchange connector provided with a ringer-relay having normally-closed ringing switch-contacts, and with a private-wiper, together with private-bank-contacts adapted to be engaged by said wiper connections 60 between the relay contacts and said private

wiper, means for energizing said relay during talking, and means whereby the private-wiper prevents connection of the contacts of said relay with a busy line.

5. A common battery automatic telephone 70 exchange connector provided with a ringer-relay having normally-open switch-contacts, and adapted for constant energization during use of the connector for talking purposes, together with a relay and means controlled thereby for putting current for talking purposes on the line of the calling subscriber, said relay being exclusively controlled by the called subscriber.

6. A common battery automatic telephone 80 exchange connector provided with a side-switch having a private-wiper, a shaft having a private-wiper, a ringer-relay having an energizing coil and a set of switch-springs, and a back-bridge-relay having an energizing coil and a set of switch-springs, together with connections whereby the said private-wiper of the side-switch is connected with the shaft private-wiper, with the ringer-relay-coil, with the back-bridge-relay-coil, and with a spring of the back-bridge-relay.

7. A common battery automatic telephone exchange system comprising a subscriber's line-circuit, a transmitter in said line-circuit, a receiver independent of but inductively connected with the said line-circuit, a ringing-key in the line-circuit, means for opening the line circuit and grounding one side thereof when the ringing key is operated, means controlled by the switch-hook for controlling said ground connection, and a ringing relay deenergized when the ringing key is pressed for supplying ringing current to any called subscriber's line, together with a centralized source of current for supplying current for talking purposes through the ringing-key and transmitter, said transmitter being disposed between the inductive connection and the ringing key.

8. A telephone system comprising an automatic exchange subscriber's line, a source of talking current, a source of ringing current, a connector provided with a ringer-relay for controlling the supply of 115 talking current to the said subscriber's line, and a local circuit for energizing said relay to close the talking circuit, the said connector having means including a private-wiper and private-bank-contacts for establishing a guarding potential for any line with which the connector makes connections, said ringer-relay controlling the continuity of connection between the two lines and the flow of ringing current to the called 120 line.

9. A telephone system comprising a subscriber's line, a centralized source of talking current, a centralized source of ringing current, a connector provided with 125

- 5 a ringer-relay adapted to control the supply of both talking and ringing current to the said line, and a circuit for energizing said relay to close the talking circuit, the said connector having means including a private-wiper and private-bank-contacts for establishing a guarding potential for any line with which the connector makes connection, said ringer-relay controlling the 10 continuity of connection to the said line.
10. A telephone system comprising a connector provided with normally open relay-contacts included in the path of the voice-currents, a back-bridge-relay for the 15 connector, said relay having one terminal permanently connected with one of said normally open relay-contacts, and said connector having means including a private-wiper and private-bank-contacts for establishing a guarding potential for any line with which the connector makes connection.
15. A telephone system comprising a connector having release mechanism operated by a release-magnet, a ringer-relay for the connector, and an energizing circuit for said magnet, the said circuit being controlled by said relay, and said connector having means including a private-wiper 20 and private-bank-contacts for establishing a guarding potential for any line with which the connector makes connection.
16. A telephone system comprising a connector, a pair of line-relays, a ringer-relay, a source of talking current, a source of ringing current, and suitable connections whereby the ringer-relay when energized is adapted to connect the line-relays in series with the source of talking current, 25 and to connect the said relays in parallel when deenergized, the said connector having means including a private-wiper and private-bank-contacts for establishing a guarding potential for any line with which the connector makes connection.
17. A telephone system comprising a line-circuit, a connector provided with a pair of line-relays and also with a release-magnet and a ringer-relay, a source of talking current, a source of ringing current, and suitable connections whereby the ringer-relay controls the supply of both talking and ringing current to the line-circuit, said ringer-relay being adapted when energized 30 to connect the two line-relays in series with the source of talking current, and when deenergized to connect the source of ringing current with the line-circuit, and the source of talking current with the line-relays in parallel, together with an energizing circuit for the said release-magnet, said energizing circuit being controlled by the ringer-relay, and said connector having means including a private-wiper and private-bank-contacts for establishing a guard- 35 ing potential for any line with which the connector makes connection.
18. A telephone system comprising a connector having release mechanism operated by a release-magnet, a ringer-relay for the connector, and an energizing circuit for said magnet, the said circuit being controlled by said relay, and the said connector having a double-wound relay adapted to be energized when its coils are connected in parallel, and adapted to remain deenergized when its two coils are connected in series, a line-circuit, a battery for supplying talking current through the said coils to the line-circuit, and a ringer-relay for the connector, together with an energizing circuit for the ringer-relay, said energizing circuit being controlled by said double-wound relay, and said connector provided with a private wiper and having means including said private-wiper and private-bank-contacts for establishing a guarding potential for any line with which the connector makes connection. 70
19. A telephone system comprising a connector, a line-circuit, a source of ringing current, and a ringer-relay for the connector, said relay being adapted when deenergized to connect the ringing-generator with the line-circuit, the said connector having means including a private-wiper and private-bank-contacts for establishing a guarding potential for any line with which the connector makes connection. 75
20. A telephone system comprising a connector, a line-circuit, a source of ringing current, and a ringer-relay for the connector, said relay being adapted when deenergized to connect the ringing-generator with the line-circuit, the said connector having means including a private-wiper and private-bank-contacts for establishing a guarding potential for any line with which the connector makes connection. 80
21. A telephone system comprising an automatic exchange subscriber's line, a source of talking current, a source of ringing current, and a connector provided with a ringer-relay having normally open contacts in the talking circuit adapted to control the supply of talking current to the said subscriber's line, the said connector having a private-wiper, together with a busy-release-circuit including said private-wiper. 85
22. A telephone system comprising a subscriber's line, a centralized source of talking current, a centralized source of ringing current, and a connector provided with a ringer-relay having normally open contacts in the talking circuit adapted to control the supply of talking and ringing current to the said line, the said connector having a private-wiper, together with a busy-release-circuit including said private-wiper. 90
23. A telephone system comprising a connector provided with normally open switch-contacts included in the path of the voice-currents, a back-bridge-relay for the connector, said relay having one terminal permanently connected with one of said switch-contacts, and said connector having a private-wiper, together with a busy-release-circuit including said private-wiper. 95
24. A telephone system comprising a connector having release mechanism operated by a release-magnet, a ringer-relay for the connector, and an energizing circuit for said magnet, the said circuit being controlled by said relay, and the said connector having a double-wound relay adapted to be energized when its coils are connected in parallel, and adapted to remain deenergized when its two coils are connected in series, a line-circuit, a battery for supplying talking current through the said coils to the line-circuit, and a ringer-relay for the connector, together with an energizing circuit for the ringer-relay, said energizing circuit being controlled by said double-wound relay, and said connector provided with a private wiper and having means including said private-wiper and private-bank-contacts for establishing a guarding potential for any line with which the connector makes connection. 100
25. A telephone system comprising a connector, a line-circuit, a source of ringing current, and a ringer-relay for the connector, said relay being adapted when deenergized to connect the ringing-generator with the line-circuit, the said connector having means including a private-wiper and private-bank-contacts for establishing a guarding potential for any line with which the connector makes connection. 105
26. A telephone system comprising an automatic exchange subscriber's line, a source of talking current, a source of ringing current, and a connector provided with a ringer-relay having normally open contacts in the talking circuit adapted to control the supply of talking current to the said subscriber's line, the said connector having a private-wiper, together with a busy-release-circuit including said private-wiper. 110
27. A telephone system comprising a subscriber's line, a centralized source of talking current, a centralized source of ringing current, and a connector provided with a ringer-relay having normally open contacts in the talking circuit adapted to control the supply of talking and ringing current to the said line, the said connector having a private-wiper, together with a busy-release-circuit including said private-wiper. 115
28. A telephone system comprising a connector provided with normally open switch-contacts included in the path of the voice-currents, a back-bridge-relay for the connector, said relay having one terminal permanently connected with one of said switch-contacts, and said connector having a private-wiper, together with a busy-release-circuit including said private-wiper. 120
29. A telephone system comprising a connector having release mechanism operated by a release-magnet, a ringer-relay for the connector, and an energizing circuit for said magnet, the said circuit being controlled by said relay, and the said connector having a double-wound relay adapted to be energized when its coils are connected in parallel, and adapted to remain deenergized when its two coils are connected in series, a line-circuit, a battery for supplying talking current through the said coils to the line-circuit, and a ringer-relay for the connector, together with an energizing circuit for the ringer-relay, said energizing circuit being controlled by said double-wound relay, and said connector provided with a private wiper and having means including said private-wiper and private-bank-contacts for establishing a guarding potential for any line with which the connector makes connection. 125
30. A telephone system comprising a connector, a line-circuit, a source of ringing current, and a ringer-relay for the connector, said relay being adapted when deenergized to connect the ringing-generator with the line-circuit, the said connector having means including a private-wiper and private-bank-contacts for establishing a guarding potential for any line with which the connector makes connection. 130

a private-wiper, together with a busy-release-circuit including said private-wiper.

20. A telephone system comprising a connector, a pair of line-relays, a ringer relay, 5 a source of talking current, a source of ringing current, and suitable connections whereby the ringer-relay when energized is adapted to connect the line-relays in series with the source of talking current, and to 10 connect the said relays in parallel when de-energized, the said connector having a private-wiper, together with a busy-release-circuit including said private-wiper.

21. A telephone system comprising a line- 15 circuit, a connector provided with a pair of line-relays and also with a release-magnet and a ringer-relay, a source of talking current, a source of ringing current, and suitable connections whereby the ringer-relay controls the supply of both talking and 20 ringing current to the line-circuit, said ringer-relay being adapted when energized to connect the two line-relays in series with the source of talking current, and when de- 25 energized to connect the source of ringing current with the line-circuit, and the source of talking current with the line-relays in parallel, together with an energizing circuit for the said release-magnet, said energizing 30 circuit being controlled by the ringer-relay, and said connector having a private-wiper, together with a busy-release-circuit including 35 said private-wiper.

22. A telephone system comprising a connector having a double-wound relay adapted 40 to be energized when its coils are connected in parallel, and adapted to remain deenergized when its two coils are connected in series, a line-circuit, a battery for supplying talking current through the said coils to the 45 line-circuit, and a ringer-relay for the connector, together with an energizing circuit for the ringer-relay, said energizing circuit being controlled by said double-wound relay, and said connector having a private-wiper, together with a busy-release-circuit including 50 said private-wiper.

23. A telephone system comprising a connector, a line-circuit, a source of ringing 55 current, and a ringer-relay for the connector, said relay being adapted when deenergized to connect the ringing-generator with the line-circuit, and said connector having a private-wiper, together with a busy-release-circuit including 60 said private-wiper.

24. A telephone system comprising an automatic exchange subscriber's line, a source of talking current, a source of ringing current, and a connector provided with a 65 ringer-relay adapted to control the supply of talking current to the said subscriber's line, the said connector having a busy-release-circuit controlled at one point by said ringer-relay, said busy release circuit being

separate from any conductor in the talking 65 circuit.

25. A telephone system comprising a subscriber's line, a centralized source of talking current, a centralized source of ringing current, and a connector provided with a 70 ringer-relay adapted to control the supply of both talking and ringing current to the said line, the said connector having a busy-release-circuit controlled at one point by said ringer-relay, said busy release circuit being 75 separate from any conductor in the talking circuit.

26. A telephone system comprising a connector provided with switch-contacts included in the path of the voice-currents, a 80 back-bridge-relay for the connector, said relay having one terminal permanently connected with one of said switch-contacts, and a ringer-relay, the said connector having a busy-release-circuit controlled at one point 85 by said ringer-relay, said busy release circuit being separate from any conductor in the talking circuit.

27. A telephone system comprising a connector having release mechanism operated by 90 a release-magnet, a ringer-relay for the connector, and an energizing circuit for said magnet, the said circuit being controlled by said relay, and said connector having a busy-release-circuit controlled at one point by 95 said ringer-relay, said busy release circuit being separate from any conductor in the talking circuit.

28. A telephone system comprising a connector, a pair of line-relays, a ringer-relay, 100 a source of talking current, a source of ringing current, and suitable connections whereby the ringer-relay when energized is adapted to connect the line-relays in series with the source of talking current, and to connect 105 the said relays in parallel when deenergized, the said connector having a busy-release-circuit controlled at one point by said ringer-relay, said busy release circuit being separate from any conductor in the talking circuit.

29. A telephone system comprising a line-circuit, a connector provided with a pair of line-relays and also with a release-magnet 115 and a ringer-relay, a source of talking current, a source of ringing current, and suitable connections whereby the ringer-relay controls the supply of both talking and ringing current to the line-circuit, said ringer-relay being adapted when energized 120 to connect the two line-relays in series with the source of talking current, and when deenergized to connect the source of ringing current with the line-circuit, and the source of talking current with the line-relays in 125 parallel, together with an energizing circuit for the said release-magnet, said energizing circuit being controlled by the ringer-relay,

and the said connector having a busy-release-circuit controlled at one point by said ringer-relay, said busy release circuit being separate from any conductor in the talking 5 circuit.

30. A telephone system comprising a connector having a double-wound relay adapted to be energized when its coils are connected in parallel, and adapted to remain deenergized when its two coils are connected in series, a line-circuit, a battery for supplying talking current through the said coils to the line-circuit, and a ringer-relay for the connector, together with an energizing circuit for the ringer-relay, said energizing circuit being controlled by said double-wound relay, and the said connector having a busy-release-circuit controlled at one point by said ringer-relay, said busy release 10 circuit being separate from any conductor in the talking circuit.

31. A telephone system comprising a connector, a line-circuit, a source of ringing current, and a ringer-relay for the connector, said relay being adapted when deenergized to connect the ringing-generator with the line-circuit, and the said connector having a busy-release-circuit controlled at one point by said ringer-relay, said busy release 15 circuit being separate from any conductor in the talking circuit.

32. A telephone system comprising an automatic exchange subscriber's line, a source of talking current, a source of ringing current, and a connector provided with a ringer-relay having normally open contacts adapted to control the supply of talking current to the said subscriber's line, the said connector having relay means controlled exclusively by any called subscriber and upon the energization of which the supply of talking current to the calling subscriber is dependent.

33. A telephone system comprising a subscriber's line, a centralized source of talking current, a centralized source of ringing current, and a connector provided with a ringer-relay having normally open contacts in the talking circuit adapted to control the supply of talking and ringing current to the said line, the said connector having relay means controlled exclusively by any called subscriber and upon the energization of which the supply of talking current to the calling subscriber is dependent.

34. A telephone system comprising a connector provided with normally open switch-contacts included in the path of the voice-currents, a back-bridge-relay for the connector, said relay having one terminal permanently connected with one of said switch-contacts, and the said connector having relay means controlled exclusively by any called subscriber and upon the energization of

which the supply of talking current to the 65 calling subscriber is dependent.

35. A telephone system comprising a connector having release mechanism operated by a release-magnet, a ringer-relay for the connector, and an energizing circuit for said magnet, the said circuit being controlled by said relay, and the said connector having relay means controlled exclusively by any called subscriber and upon the energization of which the supply of talking current to the 70 calling subscriber is dependent.

36. A telephone system comprising a connector, a pair of line-relays, a ringer-relay, a source of talking current, a source of ringing current, and suitable connections whereby the ringer-relay when energized is adapted to connect the line-relays in series with the source of talking current, and to connect the said relays in parallel when deenergized, the said connector having relay 80 means controlled exclusively by any called subscriber and upon the energization of which the supply of talking current to the calling subscriber is dependent.

37. A telephone system comprising a line-circuit, a connector provided with a pair of line-relays and also with a release-magnet and a ringer-relay, a source of talking current, a source of ringing current, and suitable connections whereby the ringer-relay 90 controls the supply of both talking and ringing current to the line-circuit, said ringer-relay being adapted when energized to connect the two line-relays in series with the source of talking current, and when deenergized to connect the source of ringing current with the line-circuit, and the source of talking current with the line-relays in parallel, together with an energizing circuit for said release-magnet, said energizing circuit 100 being controlled by the ringer-relay, and the said connector having relay means controlled exclusively by any called subscriber and upon the energization of which the supply of talking current to the calling subscriber 105 is dependent.

38. A telephone system comprising a connector having a double-wound relay adapted to be energized when its coils are connected in parallel, and adapted to remain deenergized when its two coils are connected in series, a line-circuit, a battery for supplying talking current through the said coils to the line-circuit, and a ringer-relay for the connector, together with an energizing circuit 115 for the ringer-relay, said energizing circuit being controlled by said double-wound relay, and the said connector having relay means controlled exclusively by any called subscriber and upon the energization of 120 which the supply of talking current to the calling subscriber is dependent.

39. A telephone system comprising a con-

- 5 nector, a line-circuit, a source of ringing current, and a ringer-relay for the connector, said relay being adapted when deenergized to connect the source of ringing current with the line-circuit, and the source of talking current with the line-circuit, and the said connector having a relay means controlled exclusively by any called subscriber and upon the energization of which the supply of talking current to the calling subscriber is dependent.
- 10 40. A telephone system comprising an automatic exchange subscriber's line, a source of talking current, a source of ringing current, and a connector provided with a ringer-relay adapted when energized to maintain the supply of talking current to the said subscriber's line, the said connector having a side-switch through which the calling subscriber gets current for talking purposes.
- 15 41. A telephone system comprising a subscriber's line, a centralized source of talking current, a centralized source of ringing current, and a connector provided with a ringer-relay adapted when energized to maintain the supply of talking current to the said line, and when deenergized to put ringing current on the line, the said connector having a side-switch through which the calling subscriber gets current for talking purposes.
- 20 42. A telephone system comprising a connector provided with normally open relay-contacts included in the path of the voice-currents, a back-bridge-relay for the connector, said relay having one terminal permanently connected with one of said relay-35 contacts, and the said connector having a side-switch through which the calling subscriber gets current for talking purposes.
43. A telephone system comprising a connector having release mechanism operated by a release-magnet, a ringer-relay for the connector, and an energizing circuit for said magnet, the said circuit being controlled by said relay, and the said connector having a side-switch through which the calling subscriber gets current for talking purposes.
- 45 44. A telephone system comprising a connector, a pair of line-relays, a ringer-relay, a source of talking current, a source of ringing current, and suitable connections whereby the ringer-relay when energized is adapted to connect the line-relays in series with the source of talking current, and to connect the said relays in parallel when deenergized, the said connector having a side-switch through which the calling subscriber gets current for talking purposes.
- 50 45. A telephone system comprising a line-circuit, a connector provided with a pair of line-relays and also with a release-magnet and a ringer-relay, a source of talking current, a source of ringing current, and suitable connections whereby the ringer-relay controls the supply of both talking and ringing current to the line-circuit, said ringer-relay being adapted when energized to connect the two line-relays in series with the source of talking current, and when deenergized to connect the source of ringing current with the line-circuit, and the source of talking current with the line-circuit, and the said connector having a side-switch through which the calling subscriber gets current for talking purposes.
- 55 46. A telephone system comprising a connector having a double-wound relay adapted to be energized when its coils are connected in parallel, and adapted to remain deenergized when its two coils are connected in series, a line-circuit, a battery for supplying talking current through the said coils to the line-circuit, and a ringer-relay for the connector, together with an energizing circuit for the ringer relay, said energizing circuit being controlled by said double-wound relay, and the said connector having a side-switch through which the calling subscriber gets current for talking purposes.
- 60 47. A telephone system comprising a connector, a line-circuit, a source of ringing current, and a ringer-relay for the connector, said relay being adapted when deenergized to connect the ringing-generator with the line-circuit, and the said connector having a side-switch through which the calling subscriber gets current for talking purposes.
- 65 48. A telephone exchange connector provided with a line-conductor, a condenser in said conductor, a ringer-relay having a spring in which said conductor terminates, and a back-bridge-relay having one terminal connected with said line-conductor at a point between the said condenser and the said spring, together with means controlled by said back-bridge relay, and under the exclusive control of any called subscriber, for supplying current for talking purposes to the calling line, and the exchange also comprising trunk-lines and a trunk-selecting switch provided with releasing means having a circuit controlled at one point by the ringer-relay of the connector.
- 70 49. A telephone exchange connector provided with line-circuit-conductors each having a condenser therein, and a back-bridge-relay located on the side of the condensers toward the called subscriber and adapted to be controlled exclusively by the latter, means dependent upon the energization of said relay for supplying talking current to the calling line, and a ringer-relay having at least four switch-springs, together with an energizing circuit for said back-bridge-relay, said energizing circuit including said springs, and the exchange also comprising trunk-lines and a trunk-selecting switch provided with releasing means having a circuit controlled at one point by the ringer-relay of the connector.
- 75 50. A telephone system comprising a line-circuit, a connector provided with a pair of line-relays and also with a release-magnet and a ringer-relay, a source of talking current, a source of ringing current, and suitable connections whereby the ringer-relay controls the supply of both talking and ringing current to the line-circuit, said ringer-relay being adapted when energized to connect the two line-relays in series with the source of talking current, and when deenergized to connect the source of ringing current with the line-circuit, and the source of talking current with the line-circuit, and the said connector having a side-switch through which the calling subscriber gets current for talking purposes.
- 80 51. A telephone system comprising a connector having a double-wound relay adapted to be energized when its coils are connected in parallel, and adapted to remain deenergized when its two coils are connected in series, a line-circuit, a battery for supplying talking current through the said coils to the line-circuit, and a ringer-relay for the connector, together with an energizing circuit for the ringer relay, said energizing circuit being controlled by said double-wound relay, and the said connector having a side-switch through which the calling subscriber gets current for talking purposes.
- 85 52. A telephone system comprising a connector, a line-circuit, a source of ringing current, and a ringer-relay for the connector, said relay being adapted when deenergized to connect the ringing-generator with the line-circuit, and the said connector having a side-switch through which the calling subscriber gets current for talking purposes.
- 90 53. A telephone system comprising a connector, a line-circuit, a source of ringing current, and a ringer-relay for the connector, said relay being adapted when deenergized to connect the ringing-generator with the line-circuit, and the said connector having a side-switch through which the calling subscriber gets current for talking purposes.
- 95 54. A telephone system comprising a connector, a line-circuit, a source of ringing current, and a ringer-relay for the connector, said relay being adapted when deenergized to connect the ringing-generator with the line-circuit, and the said connector having a side-switch through which the calling subscriber gets current for talking purposes.
- 100 55. A telephone system comprising a connector, a line-circuit, a source of ringing current, and a ringer-relay for the connector, said relay being adapted when deenergized to connect the ringing-generator with the line-circuit, and the said connector having a side-switch through which the calling subscriber gets current for talking purposes.
- 105 56. A telephone system comprising a connector, a line-circuit, a source of ringing current, and a ringer-relay for the connector, said relay being adapted when deenergized to connect the ringing-generator with the line-circuit, and the said connector having a side-switch through which the calling subscriber gets current for talking purposes.
- 110 57. A telephone system comprising a connector, a line-circuit, a source of ringing current, and a ringer-relay for the connector, said relay being adapted when deenergized to connect the ringing-generator with the line-circuit, and the said connector having a side-switch through which the calling subscriber gets current for talking purposes.
- 115 58. A telephone system comprising a connector, a line-circuit, a source of ringing current, and a ringer-relay for the connector, said relay being adapted when deenergized to connect the ringing-generator with the line-circuit, and the said connector having a side-switch through which the calling subscriber gets current for talking purposes.
- 120 59. A telephone system comprising a connector, a line-circuit, a source of ringing current, and a ringer-relay for the connector, said relay being adapted when deenergized to connect the ringing-generator with the line-circuit, and the said connector having a side-switch through which the calling subscriber gets current for talking purposes.
- 125 60. A telephone system comprising a connector, a line-circuit, a source of ringing current, and a ringer-relay for the connector, said relay being adapted when deenergized to connect the ringing-generator with the line-circuit, and the said connector having a side-switch through which the calling subscriber gets current for talking purposes.
- 130 61. A telephone system comprising a connector, a line-circuit, a source of ringing current, and a ringer-relay for the connector, said relay being adapted when deenergized to connect the ringing-generator with the line-circuit, and the said connector having a side-switch through which the calling subscriber gets current for talking purposes.

cuit controlled at one point by the ringer-relay of the connector.

50. A telephone exchange connector provided with a side-switch having a grounded conductor, line and private wipers, and a ringer-relay, together with an energizing circuit for said ringer-relay, said energizing circuit including said grounded conductor, and said private-wiper being also connected to receive current from the said grounded conductor when the said connector is set on a called line, the exchange also comprising trunk-lines and a trunk-selecting switch provided with releasing means having a circuit controlled at one point by the ringer-relay of the connector.

51. A common battery automatic telephone exchange connector provided with a differential-relay, and with a private-wiper, together with private-bank-contacts adapted to be engaged by said private-wiper, and a ringer-relay, the exchange also comprising trunk-lines and a trunk-selecting switch provided with releasing means having a circuit controlled at one point by the ringer-relay of the connector.

52. A common battery automatic telephone exchange connector provided with a ringer-relay having normally-closed ringing switch-contacts, and with a private-wiper, together with private-bank-contacts adapted to be engaged by said wiper, the exchange also comprising trunk-lines and a trunk-selecting switch provided with releasing means having a circuit controlled at one point by the ringer-relay of the connector.

53. A common battery automatic telephone exchange connector provided with a ringer-relay having a plurality of switch-springs, and provided with a back-bridge-relay controlled exclusively by any called subscriber for establishing current for talking purposes on the calling line, the outer spring of said ringer-relay being connected directly with one of the switch-contacts of the back-bridge-relay, and the exchange also comprising trunk-lines and a trunk-selecting switch provided with releasing means having a circuit controlled at one point by the ringer-relay of the connector.

54. A common battery automatic telephone exchange connector provided with a ringer-relay having normally-open switch-contacts, and adapted for constant energization during use of the connector for talking purposes, together with a relay and means controlled thereby for putting current for talking purposes on the line of the calling subscriber, said relay being exclusively controlled by the called subscriber, and the exchange also comprising trunk-lines and a trunk-selecting switch provided with releasing means having a circuit controlled at one point by the ringer-relay of the connector.

55. A common battery automatic telephone exchange connector provided with a side-switch having a private-wiper, a shaft having a private-wiper, a ringer-relay having an energizing coil and a set of switch-springs, and a back-bridge-relay having an energizing coil and a set of switch-springs, together with connections whereby the said private-wiper of the side-switch is connected with the shaft private-wiper, with the ringer-relay-coil, with the back-bridge-relay-coil, and with a spring of the back-bridge-relay, the exchange also comprising trunk-lines and a trunk-selecting switch provided with releasing means having a circuit controlled at one point by the ringer-relay of the connector.

56. A telephone system comprising an automatic exchange subscriber's line, a source of talking current, a source of ringing current, and a connector provided with a ringer-relay for controlling the supply of talking current to the said subscriber's line, the said connector having means including a private-wiper and private-bank-contacts for establishing a guarding potential for any line with which the connector makes connection, and the exchange also comprising trunk-lines and a trunk-selecting switch provided with releasing means having a circuit controlled at one point by the ringer-relay of the connector.

57. A telephone system comprising a subscriber's line, a centralized source of talking current, a centralized source of ringing current, and a connector provided with a ringer-relay adapted to control the supply of both talking and ringing current to the said line, the said connector having means including a private-wiper and private-bank-contacts for establishing a guarding potential for any line with which the connector makes connection, and the exchange also comprising trunk lines and a trunk-selecting switch provided with releasing means having a circuit controlled at one point by the ringer-relay of the connector.

58. A telephone system comprising a connector provided with switch-contacts included in the path of the voice-currents, a back-bridge-relay for the connector, said relay having one terminal permanently connected with one of said switch-contacts, and a ringer-relay, the said connector having means including a private-wiper and private-bank-contacts for establishing a guarding potential for any line with which the connector makes connection, and the exchange also comprising trunk-lines and a trunk-selecting switch provided with releasing means having a circuit controlled at one point by the ringer-relay of the connector.

59. A telephone system comprising a connector having release mechanism operated

by a release-magnet, a ringer-relay for the connector, and an energizing circuit for said magnet, the said circuit being controlled by said relay, and the said connector having means including a private-wiper and private-bank-contacts for establishing a guarding potential for any line with which the connector makes connection, the exchange also comprising trunk-lines and a trunk-selecting switch provided with releasing means having a circuit controlled at one point by the ringer-relay of the connector.

60. A telephone system comprising a connector, a pair of line-relays, a ringer-relay, a source of talking current, a source of ringing current, and suitable connections whereby the ringer-relay when energized is adapted to connect the line-relays in series with the source of talking current, and to connect the said relays in parallel when deenergized, the said connector having means including a private-wiper and private-bank-contacts for establishing a guarding potential for any line with which the connector makes connection, and the exchange also comprising trunk-lines and a trunk-selecting switch provided with releasing means having a circuit controlled at one point by the ringer-relay of the connector.

61. A telephone system comprising a line-circuit, a connector provided with a pair of line-relays and also with a release-magnet and a ringer-relay, a source of talking current, a source of ringing current, and suitable connections whereby the ringer-relay controls the supply of both talking and ringing current to the line-circuit, said ringer-relay being adapted when energized to connect the two line-relays in series with the source of talking current, and when deenergized to connect the source of ringing current with the line-circuit, and the source of talking current with the line-relays in parallel, together with an energizing circuit for the said release-magnet, said energizing circuit being controlled by the ringer-relay, and said connector having means including a private-wiper and private-bank-contacts for establishing a guarding potential for any line with which the connector makes connection, the exchange also comprising trunk-lines and a trunk-selecting switch provided with releasing means having a circuit controlled at one point by the ringer-relay of the connector.

62. A telephone system comprising a connector having a double-wound relay adapted to be energized when its coils are connected in parallel, and adapted to remain deenergized when its two coils are connected in series, a line-circuit, a battery for supplying talking current through the said coils to the line-circuit, and a ringer-relay for the connector, together with an energizing circuit for the ringer-relay, said ener-

gizing circuit being controlled by said double-wound relay, and said connector having means including a private-wiper and private-bank-contacts for establishing a guarding potential for any line with which the connector makes connection, the exchange also comprising trunk-lines and a trunk-selecting switch provided with releasing means having a circuit controlled at one point by the ringer-relay of the connector.

63. A telephone system comprising a connector, a line-circuit, a source of ringing current, and a ringer-relay for the connector, said relay being adapted when deenergized to connect the ringing-generator with the line-circuit, and the said connector having means including a private-wiper and private-bank-contacts for establishing a guarding potential for any line with which the connector makes connection, the exchange also comprising trunk-lines and a trunk-selecting switch provided with releasing means having a circuit controlled at one point by the ringer-relay of the connector.

64. A telephone system comprising an automatic exchange subscriber's line, a source of talking current, a source of ringing current, and a connector provided with a ringer-relay adapted to control the supply of talking current to the said subscriber's line, the said connector having a private-wiper, together with a busy-release-circuit including said private-wiper, and the exchange also comprising trunk-lines and a trunk-selecting switch provided with releasing means having a circuit controlled at one point by the ringer-relay of the connector.

65. A telephone system comprising a subscriber's line, a centralized source of talking current, a centralized source of ringing current, and a connector provided with a ringer-relay adapted to control the supply of both talking and ringing current to the said line, the said connector having a private-wiper, together with a busy-release-circuit including said private-wiper, and the exchange also comprising trunk-lines and a trunk-selecting switch provided with releasing means having a circuit controlled at one point by the ringer-relay of the connector.

66. A telephone system comprising a connector provided with switch-contacts included in the path of the voice-currents, a back-bridge-relay for the connector, said relay having one terminal permanently connected with one of said switch-contacts, and a ringer-relay, the said connector having a private-wiper, together with a busy-release-circuit including said private-wiper, and the exchange also comprising trunk-lines and a trunk-selecting switch provided with releasing means having a circuit controlled at one point by the ringer-relay of the connector.

67. A telephone system comprising a con-

5 nector having release mechanism operated by a release-magnet, a ringer-relay for the connector, and an energizing circuit for said magnet, the said circuit being controlled by
 10 5 said relay, and the said connector having a private-wiper, together with a busy-release-circuit including said private-wiper, the exchange also comprising trunk-lines and a trunk-selecting switch provided with releasing means having a circuit controlled at one point by the ringer-relay of the connector.

15 68. A telephone system comprising a connector, a pair of line-relays, a ringer-relay, a source of talking current, a source of ringing current, and suitable connections whereby the ringer-relay when energized is adapted to connect the line-relays in series with the source of talking current, and to connect the said relays in parallel when deenergized,
 20 20 the said connector having a private-wiper, together with a busy-release-circuit including said private-wiper, and the exchange also comprising trunk-lines and a trunk-selecting switch provided with releasing
 25 25 means having a circuit controlled at one point by the ringer-relay of the connector.

30 69. A telephone system comprising a line-circuit, a connector provided with a pair of line-relays and also with a release-magnet
 35 30 and a ringer-relay, a source of talking current, a source of ringing current, and suitable connections whereby the ringer-relay controls the supply of both talking and ringing current to the line-circuit, said ringing
 40 35 relay being adapted when energized to connect the two line-relays in series with the source of talking current, and when deenergized to connect the source of ringing current with the line-circuit, and the source
 45 40 of talking current with the line-relays in parallel, together with an energizing circuit for the said release-magnet, said energizing circuit being controlled by the ringer-relay, and the said connector having a private-
 50 45 wiper, together with a busy-release-circuit including said private-wiper, the exchange also comprising trunk-lines and a trunk-selecting switch provided with releasing
 55 50 means having a circuit controlled at one point by the ringer-relay of the connector.

60 70. A telephone system comprising a connector having a double-wound relay adapted to be energized when its coils are connected in parallel, and adapted to remain deenergized when its two coils are connected in series, a line-circuit, a battery for supplying talking current through the said coils to the line-circuit, and a ringer-relay for the connector, together with an energizing circuit
 65 60 for the ringer-relay, said energizing circuit being controlled by said double-wound relay, and the said connector having a private-wiper, together with a busy-release-circuit including said private-wiper, the exchange
 70 65 also comprising trunk-lines and a trunk-se-

lecting switch provided with releasing means having a circuit controlled at one point by the ringer-relay of the connector.

75 71. A telephone system comprising a connector, a line-circuit, a source of ringing current, and a ringer-relay for the connector, said relay being adapted when deenergized to connect the ringing-generator with the line-circuit, and the said connector having a private-wiper, together with a busy-release-circuit including said private-wiper, the exchange also comprising trunk-lines and a trunk-selecting switch provided with releasing means having a circuit controlled at one point by the ringer-relay of the connector. 80

85 72. A telephone system comprising an automatic exchange subscriber's line, a source of talking current, a source of ringing current, and a connector provided with a ringer-relay adapted to control the supply of talking current to the said subscriber's line, the said connector having relay means controlled exclusively by any called subscriber and upon the energization of which the supply of talking current to the calling subscriber is dependent, and the exchange also comprising trunk-lines and a trunk-selecting switch provided with releasing means having a circuit controlled at one point by the ringer-relay of the connector. 90

95 73. A telephone system comprising a subscriber's line, a centralized source of talking current, a centralized source of ringing current, and a connector provided with a ringer-relay adapted to control the supply of both talking and ringing current to the said line, the said connector having relay means controlled exclusively by any called subscriber and upon the energization of which the supply of talking current to the calling subscriber is dependent, and the exchange also comprising trunk-lines and a trunk-selecting switch provided with releasing means having a circuit controlled at one point by the ringer-relay of the connector. 100

105 74. A telephone system comprising a connector provided with switch-contacts included in the path of the voice-currents, a back-bridge-relay for the connector, said relay having one terminal permanently connected with one of said switch-contacts, and a ringer-relay, the said connector having relay means controlled exclusively by any called subscriber and upon the energization of which the supply of talking current to the calling subscriber is dependent, and the exchange also comprising trunk-lines and a trunk-selecting switch provided with releasing means having a circuit controlled at one point by the ringer-relay of the connector. 115

115 75. A telephone system comprising a connector having release mechanism operated by a release-magnet, a ringer-relay for the connector, and an energizing circuit for said magnet, the said circuit being controlled by 120

- 5 said relay, and the said exchange having relay means controlled exclusively by any called subscriber and upon the energization of which the supply of talking current to the calling subscriber is dependent, the exchange also comprising trunk-lines and a trunk-selecting switch provided with releasing means having a circuit controlled at one point by the ringer-relay of the connector;
- 6 76. A telephone system comprising a connector, a pair of line-relays, a ringer-relay, a source of talking current, a source of ringing current, and suitable connections whereby the ringer-relay when energized is 70 adapted to connect the line-relays in series with the source of talking current, and to connect the said relays in parallel when de-energized, the said connector having relay means controlled exclusively by any called subscriber and upon the energization of which the supply of talking current to the calling subscriber is dependent, and the exchange also comprising trunk-lines and a trunk-selecting switch provided with releasing means having a circuit controlled at one point by the ringer-relay of the connector;
77. A telephone system comprising a line-circuit, a connector provided with a pair of line-relays and also with a release-magnet and a ringer-relay, a source of talking current, a source of ringing current, and suitable connections whereby the ringer-relay controls the supply of both talking and ringing current to the line-circuit, said ringer-relay being adapted when energized to connect the two line-relays in series with the source of talking current and when de-energized to connect the source of ringing current with the line-circuit, and the source of 80 talking current with the line-relays in parallel, together with an energizing circuit for the said release-magnet, said energizing circuit being controlled by the ringer-relay, and the said connector having relay means controlled exclusively by any called subscriber and upon the energization of which the supply of talking current to the calling subscriber is dependent, the exchange also comprising trunk-lines and a trunk-selecting switch provided with releasing means having a circuit controlled at one point by the ringer-relay of the connector;
78. A telephone system comprising a connector having a double-wound relay adapted to be energized when its coils are connected in parallel, and adapted to remain de-energized when its two coils are connected in series, a line-circuit, a battery for supplying talking current through the said coils to the line-circuit, and a ringer-relay for the connector, together with an energizing circuit for the ringer-relay, said energizing circuit being controlled by said double-wound relay, and the said connector having relay means controlled exclusively by any called subscriber and upon the energization of which the supply of talking current to the calling subscriber is dependent, the exchange also comprising trunk-lines and a trunk-selecting switch provided with releasing means having a circuit controlled at one point by the ringer-relay of the connector;
79. A telephone system comprising a connector, a line-circuit, a source of ringing current, and a ringer-relay for the connector, said relay being adapted when de-energized to connect the ringing-generator with the line-circuit, and the said connector having relay means controlled exclusively by any called subscriber and upon the energization of which the supply of talking current to the calling subscriber is dependent, the exchange also comprising trunk-lines and a trunk-selecting switch provided with releasing means having a circuit controlled at one point by the ringer-relay of the connector;
80. A telephone system comprising an automatic exchange subscriber's line, a source of talking current, a source of ringing current, and a connector provided with a ringer-relay adapted to control the supply of talking current to the said subscriber's line, the said connector having a side-switch through which the calling subscriber gets current for talking purposes, and the exchange also comprising trunk-lines and a trunk-selecting switch provided with releasing means having a circuit controlled at one point by the ringer-relay of the connector;
81. A telephone system comprising a subscriber's line, a centralized source of talking current, a centralized source of ringing current, and a connector provided with a ringer-relay adapted to control the supply of both talking and ringing current to the said line, the said connector having a side-switch through which the calling subscriber gets current for talking purposes, and the exchange also comprising trunk-lines and a trunk-selecting switch provided with releasing means having a circuit controlled at one point by the ringer-relay of the connector;
82. A telephone system comprising a connector provided with switch-contacts included in the path of the voice-currents, a back-bridge-relay for the connector, said relay having one terminal permanently connected with one of said switch-contacts, and a ringer-relay, the said connector having a side-switch through which the calling subscriber gets current for talking purposes, and the exchange also comprising trunk-lines and a trunk-selecting switch provided with releasing means having a circuit controlled at one point by the ringer-relay of the connector;
83. A telephone system comprising a connector, a line-circuit, a battery for supplying talking current through the said coils to the line-circuit, and a ringer-relay for the connector, together with an energizing circuit for the ringer-relay, said energizing circuit being controlled by said double-wound relay, and the said connector having relay means controlled exclusively by any called subscriber and upon the energization of which the supply of talking current to the calling subscriber is dependent, the exchange also comprising trunk-lines and a trunk-selecting switch provided with releasing means having a circuit controlled at one point by the ringer-relay of the connector;

5 nector having release mechanism operated by a release-magnet, a ringer-relay for the connector, and an energizing circuit for said magnet, the said circuit being controlled by said relay, and the said connector having a side-switch through which the calling subscriber gets current for talking purposes, the exchange also comprising trunk-lines and a trunk-selecting switch provided with 10 releasing means having a circuit controlled at one point by the ringer-relay of the connector.

15 84. A telephone system comprising a connector, a pair of line-relays, a ringer-relay, a source of talking current, a source of ringing current, and suitable connections whereby the ringer-relay when energized is adapted to connect the line-relays in series with the source of talking current, and to connect 20 the said relays in parallel when de-energized, the said connector having a side-switch through which the calling subscriber gets current for talking purposes, and the exchange also comprising trunk-lines and a 25 trunk-selecting switch provided with releasing means having a circuit controlled at one point by the ringer-relay of the connector.

30 85. A telephone system comprising a line-circuit, a connector provided with a pair of line-relays and also with a release-magnet and a ringer-relay, a source of talking current, a source of ringing current, and suitable connections whereby the ringer-relay controls the supply of both talking and 35 ringing current to the line-circuit, said ringer-relay being adapted when energized to connect the two line-relays in series with the source of talking current, and when de-energized to connect the source of ringing 40 current with the line-circuit, and the source of talking current with the line-relays in parallel, together with an energizing circuit for the said release-magnet, said energizing circuit being controlled by the ringer-relay, 45 and the said connector having a side-switch through which the calling subscriber gets current for talking purposes, the exchange also comprising trunk-lines and a trunk-selecting switch provided with releasing 50 means having a circuit controlled at one point by the ringer-relay of the connector.

55 86. A telephone system comprising a connector having a double-wound relay adapted to be energized when its coils are connected in parallel, and adapted to remain de-energized when its two coils are connected in series, a line-circuit, a battery for supplying talking current through the said coils to the line-circuit, and a ringer-relay for the 60 connector, together with an energizing circuit for the ringer-relay, said energizing circuit being controlled by said double-wound relay, and the said connector having a side-switch through which the calling subscriber gets current for talking purposes,

the exchange also comprising trunk-lines and a trunk-selecting switch provided with releasing means having a circuit controlled at one point by the ringer-relay of the connector.

70

87. A telephone system comprising a connector, a line-circuit, a source of ringing current, and a ringer-relay for the connector, said relay being adapted when de-energized to connect the ringing generator 75 with the line-circuit, and the said connector having a side-switch through which the calling subscriber gets current for talking purposes, the exchange also comprising trunk-lines and a trunk-selecting switch provided 80 with releasing means having a circuit controlled at one point by the ringer-relay of the connector.

85 88. In a telephone exchange system, the combination of a talking circuit, a ringer-relay energized to maintain the continuity of both sides of said circuit, means independent of said circuit for guarding the called line against seizure, and means for ringing the called subscriber by the de-energizing of said relay.

90 89. In a telephone exchange system, the combination of telephone lines, a talking circuit, a relay energized to maintain the continuity of both sides of said talking circuit, and means independent of said talking circuit for electrically preventing seizure of the called line.

95 90. In a telephone system, a calling line and a called line, means for establishing a talking circuit between the two comprising a connector switch, a centralized battery having one terminal connected with one side of said talking circuit, an auxiliary circuit for connecting the other terminal of said battery with the other side of the talking circuit for supplying the talking circuit with current for talking purposes, said auxiliary circuit having a break at two points, a first relay and a second relay, a circuit 100 for said first relay for controlling said first relay to close one of said breaks, a circuit for said second relay under the control of the called subscriber for controlling said relay to close the other break in said circuit, 105 whereby the supply of talking current to the talking circuit is controlled by the called subscriber.

110 91. In a telephone system, a calling line and a called line, means for establishing a talking circuit between the two comprising a connector switch, a centralized battery having one terminal connected with one side of said talking circuit, an auxiliary circuit for connecting the other terminal of said battery with the other side of the talking circuit for supplying the talking circuit with current for talking purposes, said auxiliary circuit having a break at two points, a first relay and a second relay, an energiz- 115 120 125 130

ing circuit for said first relay for operating said first relay to close one of said breaks, an energizing circuit for said second relay under the control of the called subscriber for operating said relay to close the other break in said energizing circuit, whereby the supply of talking current to the talking circuit is controlled by the called subscriber.

92. In a telephone system, a calling and 10 a called line, means comprising an automatic switch for establishing a talking circuit between the two lines, a centralized battery having one terminal connected to one side of the talking circuit through suitable 15 impedance, an auxiliary circuit for connecting the other terminal of the battery with the other side of the talking circuit, a first relay and a second relay for jointly closing said circuit, means for energizing the second 20 relay when connection is made with the called line, and means for energizing the other relay when the called subscriber answers.

93. In a telephone system, a calling and a 25 called line, means comprising an automatic switch for establishing a talking circuit between the two lines, a centralized battery having one terminal connected to one side of the talking circuit through suitable impedance, an auxiliary circuit for connecting the other terminal of the battery with the other side of the talking circuit, a first relay and a second relay for jointly closing said circuit, means for energizing the second re-

lay when connection is made with the called 35 line, and means for energizing the other relay when the called subscriber answers, and means for signaling the called line controlled by said first relay.

94. In a telephone system, a calling line 40 and a called line, means for establishing a talking circuit between the two comprising a connector switch, a centralized battery having one terminal connected with one side of said talking circuit, an auxiliary circuit 45 for connecting the other terminal of said battery with the other side of the talking circuit for supplying the talking circuit with current for talking purposes, said auxiliary circuit having a break at two points, a first relay and a second relay, an energizing circuit for said first relay for operating said first relay to close one of said breaks, an energizing circuit for said second relay under the control of the called subscriber for operating said second relay to close the other break in said energizing circuit, whereby the supply of talking current to the talking circuit is controlled by the called subscriber, and means for signaling the called line controlled by said first relay.

Signed by me at Chicago, Cook county, Illinois, this 14 day of Dec., 1905.

TALBOT G. MARTIN.
